MACHINE FOR OPERATING UPON SHOES

Ernest W. Stacey, Beverly, Mass., assignor to
United Shoe Machinery Corporation, Paterson,
N. J., a corporation of New Jersey

Application March 28, 1933, Serial No. 663,121

133 Claims. (Cl. 12—80)

This invention relates to machines for treating the lower peripheral portions of shoes. It is herein illustrated as embodied in a machine for applying cement to rubber-soled shoes of the tennis type around the foxing area, for example.

Large quantities of shoes of the tennis or sneaker type are manufactured at such a low cost that the rapid and uniform accomplishment of the various shoemaking operations is of great consequence. Substantially all these shoes are provided with rubber soles. These soles are cemented to the bottom of the shoe and are also secured around the periphery of the shoe by attachment to a foxing strip of unvulcanized rubber which is applied to the periphery of the shoe and is held there by an underlying coating of cement. It is necessary for the production of satisfactory work that the cement on the foxing area shall be applied in a coat of substantial thickness which should be substantially uniform and which must be so carefully located upon the shoe that the upper edge of the line of cement will coincide accurately with the position at which it is desired to place the upper edge of the foxing strip, thereby to secure firm attachment of the strip and avoid the application of cement in such a way that it will not be covered by the foxing strip. A satisfactory machine for carrying out this operation must be capable of producing work of the desired quality at a speed such that the time allowed for the operation is only a few seconds.

One important object of my invention is to provide an improved machine for operating upon the lower peripheral portions of shoes which will enable the shoes to be presented to the machine and withdrawn therefrom with facility, thus reducing the amount of idle time between successive cycles or operations of the machine and enabling increased production.

In the attainment of this object a feature of the invention resides in the provision, in a machine of the type which provides for relative movement between the shoe and an operating tool, of shoe-supporting mechanism having relatively movable clamping members designed to hold the shoe in a substantially upright position by engagement with the top of the shoe or its last, leaving the bottom of the shoe unobstructed for the action of the tool. In cementing, an excess of cement may be applied and the unused portion of the cement drained without damaging other parts of the shoe. This excess cement is caught and re-delivered to the tool. In the illustrated construction the tool is yield-

ingly mounted, at a substantially fixed position on the machine, and the shoe support or jack carries the shoe around to present successive portions of the periphery of the shoe to the tool.

In accordance with other features of the invention and as illustrated, the shoe supporting jack is mounted on the lower end of a post, depending from the machine along a downwardly, forwardly inclined axis. Provision is made for moving the jack with both turning and straight-line movements so as to impart to the periphery of the shoe a substantially constant linear velocity. The jack is made adjustable for different sizes of shoes and novel mechanism is provided to release the clamping mechanism of the jack in any position of the shoe. The invention also provides improved driving mechanism for the jack comprising, in the illustrated machine, a pinion in engagement with an internal, continuous rack. As shown also, this rack is adjustable to take care of different sizes of shoes.

In order to make sure that the cement is applied around the whole periphery, for example, leaving no gap, the machine is arranged to carry the shoe through more than one complete peripheral movement, and is automatic, provision being made for a reverse movement to secure a uniform starting position. In accordance with still other features of the invention, the machine is arranged automatically to bring the tool into contact with the shoe, to turn the shoe to act upon more than the full periphery, and then to withdraw the tool and at the same time to reverse the movement of the shoe to bring it back to the starting position. With the machine constructed thus, the operator grasps a shoe by the bottom with her right hand, lifts it up into engagement with the jack, depresses the starting treadle which allows the jack to grip the shoe, and causes the machine to go through its cycle of operations. At the completion of this cycle, the above-mentioned reverse movement takes place which terminates at a predetermined position and the operator is thereby able, without excessive care, to present her left hand at a position where she can grasp the upper part of the shoe at the termination of the reverse movement, this movement causing the shoe to approach her hand and making it very easy for her to receive the shoe as it is released from the clamping mechanism without getting her hands into the cement and with a minimum of skill. The machine also provides novel mechanism for controlling the amount of overlap or movement of

the shoe beyond that required to traverse the whole periphery once.

Still another object of the invention is to provide an improved construction of cement-applying tool by means of which a heavy and complete coating of cement may be applied regardless of the rapidity of movement of the shoe past the tool. To this end, and in accordance with still other features of the invention, the tool for applying cement to the foxing area of the shoe comprises a curved nozzle delivering a stream of cement across a very narrow gap directly upon the foxing area. This nozzle is guided for swinging movement about an axis which substantially coincides with the upper edge of the foxing area, when the tool is in operative relation to the shoe. The illustrated construction provides a supply pipe for the nozzle which is pivoted, at a point spaced from the nozzle, for rotation about the same axis as is the nozzle.

Preferably, and as shown, the tool is mounted upon an arm which is swingable to carry the tool toward and away from the shoe and heightwise of the shoe. This arm, in the illustrated machine, is controlled by a cam to draw it positively away from the shoe at the completion of the operation and to bring it forward into engagement with the shoe at the beginning of the operation. After the tool engages the shoe, the tool-carrying arm is released from control of the cam and is held yieldably in contact with the shoe.

To facilitate bringing the tool into engagement with the shoe at just the desired position and to control the tool when in contact with the shoe, there is provided a bottom rest inclined forwardly and downwardly with respect to the shoe bottom. A bottom-engaging member is also provided which contacts with spaced points upon the bottom of a shoe enabling the upper edge of the foxing area to be located as desired, such as along a straight line from the ball line rearwardly to the heel portion of the shoe.

In order that the bottom of the shoe may also be coated simultaneously with the foxing area, the illustrated machine is provided with an improved tool for directing a stream of cement upon the bottom of a shoe. Many tennis shoes are provided with a toe cap, usually of sheet rubber, which is cemented upon the toe of the shoe. To provide for this application of cement to the toe-cap area, the machine, as illustrated, includes also a novel tool for applying cement to this toe-cap area during the application of cement to other parts of the shoe. As shown, this tool comprises an applying nozzle delivering a curtain of cement into which the toe of the shoe moves during its progress past the foxing-cementing tool. At a predetermined point, depending upon the desired location of the rear edge of the toe-cap area, this tool is dropped into engagement with the shoe and is then dragged toward the toe end of the shoe and out of the range of movement of the shoe. This toe-cap cementing tool, in the illustrated machine, also embodies features of invention which may be included in the foxing-cementing tool or the bottom-cementing tool to enable the production of a coating of uniform thickness. For this purpose the tool has adjacent to the nozzle a wick surrounded by a coil of wire. The wick is held away from the shoe a predetermined distance by the coil of wire and evens or levels the coating of cement applied by the nozzle to a thickness determined by the diameter of the wire around the wick.

Referring to the accompanying drawings,

Fig. 13 is an elevation of another portion of this same mechanism;

Fig. 14 is a view principally in perspective showing the adjustable stop of the mechanism for controlling the overlap;

Fig. 15 is a vertical cross-section on the line XV—XV of Fig. 12 through the mechanism for controlling the overlap;

Fig. 16 is a detail showing how the hub of a shifting lever is fastened to the shaft;

Fig. 17 is a vertical section on the line XVII—XVII of Fig. 3 through the same lever which is shown in Fig. 16 showing also a part of the mechanism for shifting the driving shaft longitudinally;

Fig. 18 is a side elevation with parts in section which shows the mechanism for actuating the shifting lever which moves the driving shaft longitudinally and which is partly shown, on a smaller scale, at the right of Fig. 3;

Fig. 19 is a view principally in end elevation of the controlling cams shown in side elevation in Fig. 18 and which cuts some parts on the line XIX—XIX of Fig. 18;

Fig. 20 is a vertical section through the same cams on the line XX—XX of Fig. 18;

Fig. 21 is a view in the direction of the arrow XXI in Fig. 1 looking down upon the cement-applying mechanism and the catch-basin or drain board for cement which is located beneath it, and taken in a plane which is at forty-five degrees to the horizontal and hence is parallel to the axis of the jack shaft;

Fig. 22 is a view in the direction of the arrow XXII in Fig. 1, and partly in section, looking down upon the cement-applying mechanism and its mounting;

Fig. 23 is a detail in side elevation on a greatly enlarged scale showing a part of the foxing cementing tool;

Fig. 24 is a side elevation of the foxing cementing tool and the segmental member in which it is mounted taken from the left of Fig. 22;

Fig. 24^a is a detail in section showing the outlet openings of the foxing cementing tool;

Fig. 25 is a plan, viewed from the under side 10 and in the direction of the arrow XXV in Fig. 3, of the cam and its associated mechanism which acts to swing the foxing cementing tool into contact with the shoe, to hold it in contact with the shoe during the cementing operation, and finally 15 to withdraw it from the shoe at the end of that operation;

Fig. 26 is a vertical section from side to side of the cement-supply tank on the line XXVI—XXVI of Fig. 1 and showing the mechanism for forcing cement from the tank to the foxing cementing tool;

Fig. 27 is a section on the line XXVII—XXVII of Fig. 26 showing the stirrer in the cement-supply tank;

Fig. 28 is a section on the line XXVIII—XXVIII of Fig. 26 showing the cement pump;

Fig. 29 is a section on the line XXIX—XXIX of Fig. 26 showing a part of the connection of the pump shaft with its driving shaft;

Fig. 30 is a section on the line XXX—XXX of Fig. 26 showing the same connection;

Fig. 31 is a detail principally in section of the relief valve in the cement-supply line;

Fig. 32 is a section on the line XXXII—XXXII of Fig. 31;

Figs. 33 to 36, inclusive, show the shoe in various positions which it occupies during the cementing operation;

Fig. 37 is an elevation viewed in the direction opposite to Fig. 1 and showing more particularly the toe cap cementing mechanism;

Fig. 38 is a section through the toe cap cementing tool and the valve which controls the flow of cement to the shoe;

Fig. 39 is a view partly in section and partly in elevation showing more particularly the construction of the toe cap cementing tool;

Fig. 40 is a view looking down upon the toe cap cementing tool and the structure by which it is carried;

Fig. 41 is a cross-section through the jack supporting post, and normal thereto, looking down upon a portion of the jack and a portion of the mechanism for moving the toe cap cementing tool into place over the toe portion of the shoe;

Fig. 42 is a section through a portion of the toe cap cementing mechanism taken in a plane parallel to the plane of Fig. 40 and showing the parts as they appear when the toe cap cementing tool is in its withdrawn, inoperative position;

Fig. 43 is a vertical section on the line XLIII—XLIII of Fig. 42 through the arm or yoke which carries the toe cap cementing tool, the parts being in the same positions shown in Fig. 42;

Fig. 44 is an elevation, from the front of the machine, of an alternative form of shoe bottom rest provided with means for applying cement to the bottom of a shoe which is shown in process to of being operated upon;

Fig. 45 is an end elevation, from the left, of the mechanism and a section of the shoe shown in Fig. 44;

Fig. 46 is a view looking down upon the mech-

anism shown in Fig. 44, the shoe being removed; and

Fig. 47 is a section through a portion of the bottom rest mechanism showing more particularly the compartment from which cement is forced out against the bottom of the shoe.

Referring first to Figures 1 and 3 which, when placed one above the other, show the whole machine in side elevation, the machine comprises a base or frame A in which most of the driving mechanism is contained, an adjustable carrier B for the cement-applying mechanism, and a head C bolted to the base. Mounted in the head C is a shoe support or jack D in which the shoe is held and which is moved to present the foxing area of the shoe to the cement-applying tool of the cement-applying mechanism. The shoe 109 is held with its heightwise axis inclined at about 45° to the vertical since it has been found that this position permits the operator to present and remove the shoe from the jack with the least effort. The carrier B is adjustable along similarly inclined guideways formed on the base to provide for shoes of different heights, the adjustment of the carrier being made by turning two long, heavy screws, one of which is shown at 500 in Fig. 1, said screws being held from longitudinal movement and being threaded into the carrier B. The supporting member or base plate of the carrier B is shown in Fig. 25 together with the manner in which it is held on the inclined guideway formed on the base A. The cement-applying tool is mounted for yielding movement toward and from the shoe, for movement heightwise of the shoe and for rocking movement, so as to follow the contour of the foxing area as the shoe is moved past it; and the jack is actuated in such a manner as to cause the foxing area of the shoe to travel past the cement-applying tool. In the position of rest of the parts of the machine, as shown in Figs. 1 and 3, the shoe-holding parts of the jack are in unlocked position ready to receive the shoe, and the cement-applying tool is in its withdrawn inoperative position. In the use of the machine, the operator presents a shoe to the jack in the position of the shoe 109 of Fig. 1, holds it in that position and steps upon a treadle whereupon the following movements take place. The shoe is locked rigidly to the jack, the cement-applying tool is moved into contact with the shoe, and the jack begins what will be termed its "forward movement." The forward movement of the jack causes the foxing area of the shoe to be traversed by the cement-applying tool from the point at which the tool first contacts with the shoe around the shoe and back to a point a little beyond the starting point so that the ends of the coating of cement will overlap somewhat. The cement-applying operation is now complete, but the parts must be returned to their initial positions. To this end, the cement-applying tool is withdrawn from the shoe, and the movement of the jack is reversed. During this partial backward movement of the jack the shoe is returned to its initial position where it stops, and the shoe is unlocked. Thus the operator has only to present a shoe to the jack and to depress the treadle whereupon the shoe is locked in place on the jack, cemented, returned to initial position, unlocked and brought to rest; and inasmuch as the initial position of the jack and the extent of its travel are always the same for any given adjustment of the parts of the machine for a given size of shoe, all shoes are operated upon in exactly the same manner. There is also provided, as has been ex-

plained, so-called "toe cap cementing mechanism," which may be used if desired to apply a coating of cement to the toe portion of the upper of the shoe to which a toe cap may be later applied.

The jack

Referring now more particularly to Figs. 4 to 8, the jack and its movements will be described. The base of the jack is a rigid elongated boxlike structure open at the top and bottom and having side walls 23, each of said side walls being provided on the inside with a rack in the form of two rows of teeth 27 (Fig. 5). Between the toe ends of these side walls (the right-hand ends as viewed in Figs. 4, 5 and 6) is a block 25 which is tongued into grooves formed in the side walls and fastened in place by screws, said block having a depending portion (Fig. 5) to support part of the mechanism which locks the shoe to the jack, as will later appear. Rigidly fastened to the upper side of the base of the jack is a heel-end guide member 29 which is adapted, together with another similar but adjustable toe-end 33 at the other end of the jack to be held at times in contact with a straight stationary guide-rail 37 (Fig. 7), and thus to guide the jack in its movement. The effective portion of this heel-end guide member 29 is U-shaped, the outlines of the curved end of this portion, inside and outside, being semi-circles. Located in spaced relation beneath the guide member 29 between the side walls 23 of the base of the jack is a block 30 (Fig. 5) having a wall which is U-shaped in cross-section and which registers with the inner U-shaped wall of the guide member 29, said block being fastened to the walls 23 of the base of the jack by screws some of which are shown at 32 (Fig. 4). Upon the U-shaped wall of the block 30 is formed a rack the teeth 31 of which have the same pitch as the teeth of the straight racks on the side walls 23 of the base of the jack and form a continuation of the straight racks. The forward teeth of this rack on the block 30, that is the teeth on the ends of the arms of the U, are shorter heightwise of the jack than are the teeth on the curved base of the U to permit them to lie between the two rows of teeth 27 which form the straight racks on each of the side walls 23. The block 30 has narrow ribs on its sides which are located in grooves in the side walls 23 of the jack, said block being fastened to said side walls by the screws 32, as has been stated. The toe-end guide member 33, which is like the member 29, is adjustably carried at the toe end of the base of the jack. Located in spaced relation beneath this guide member 33 and between the walls 23 of the base of the jack is a block 34 (Fig. 5). This block has a sliding tongue-and-groove connection with the walls 23 and is rigidly fastened to the guide member 33 by two side plates 36 and screws 38. The effective portion of the toe-end guide member 33 is U-shaped like the heel-end guide member 29; and the block 34, like the block 30, has on its inner U-shaped wall a U-shaped rack like the rack 31 of the block 30. The two straight racks with the two curved racks, one at each end of the straight racks, thus form an endless rack having straight sides and semi-circular ends, the pitch of the teeth of this endless rack being the same throughout so that, when the rack is engaged and driven by a pinion 55 (Fig. 2) rotating at constant velocity, the rack travels at a constant linear velocity past the cementing tool.

75 The rack is adjustable as to length, the length of

the rack for any given shoe being made substantially the same as that of the shoe; and inasmuch as the outline of the bottom of the shoe does not differ greatly from the outline of the rack, the part of the shoe being operated upon travels at a substantially constant linear velocity past the tool. The toe end member 33 and its block 34 are adjustably fastened to the base of the jack by a key 35 (Fig. 8) which is vertically slidable, as viewed in that figure, and the opposite sides of 10 which have spaced tapered projections 34' which may be slid between any two teeth on the adjacent side walls 23 of the jack, the construction being such that adjustment of the member 33 can be made only for the distance between two 15 teeth of the racks or for some multiple of that distance. Thus, whatever may be the position of the adjustable toe member 33, there is always provided on the jack an endless rack having two straight parallel sides and two semi-circular 20 ends. This key 35 has slots to receive spacing studs 36' (also shown in Fig. 7) secured to the block 34. It is guided in its sliding movement by a thin plate 38' fastened to the outer ends of the studs 36' on the block 34 and is urged upwardly 25 at all times, as far as the upper studs 36' will permit, by a coiled spring 40 (Figs. 5 and 8). This spring rests with its lower end upon a part of the base of the block 34 and engages with its upper end a flange 35' riveted to the key 35. Two 30 downwardly extending fingers, integral with the key, have horizontally extending extremities 35'' so that they may readily be grasped when it is desired to pull down the key. This needs to be depressed only far enough so that the spaced projections 34' straddle the lower rack 27, in order to free the member 33 so that it may be adjusted along the base of the jack into a position corresponding to the size of the shoe which is to be operated upon. Arranged to contact at all times 40 either with the toe member 33 or with the heel member 29, or with both of these members, is a straight stationary guide in the form of the rail 37, referred to above, which is carried by the head 45 C of the machine.

The jack is suspended from the head of the machine in such manner that it is always free, when permitted to do so, either to slide in the direction of its length or to rotate about the center of one or the other of the curved outer faces of the 50 guide members 29, 33, and is driven by the pinion 55 meshing with the endless rack, said pinion holding the curved end of the member 29 or the curved end of the member 33, or both, against the guide-rail. Assuming that the jack is in its position of rest, as shown in Figs. 6 and 33 and that power is applied in the proper direction to the endless rack, the jack will first rotate 90° counterclockwise about the center of curvature of the 55 curved outer face of the toe member 33 until the heel member 29 is brought into contact with the guide-rail 37 so that no further rotation can take place. The jack will then slide along the rail 37 with both members 29 and 33 in contact with the rail (in an upward direction as viewed in Fig. 65 7 or to the left in Fig. 34) until it is stopped in a manner presently to be described. It will then rotate counterclockwise 180° (Fig. 35) about the center of curvature of the outer face of the heel member 29 until the toe member 33 strikes the 70 guide-rail 37. It will then slide along the rail until stopped again and then rotate again (Fig. 36) about the center of curvature of the outer curved face of the toe member 33. As will be explained, mechanism is provided for stopping 75

the jack at the proper time, but during the time that the jack is driven forward it moves in the path described above which consists of alternate straight-line movements and movements of rotation.

Referring now more particularly to Figs. 5 and 6, the mounting of the jack and the pinion for driving it will be described. Formed in the side walls 23 of the base of the jack are two long grooves, one of which is shown at 39 in Fig. 5, into which extend two flanges 43' (Fig. 8) formed on opposite sides of a rectangular plate 43 which is integral with a sleeve 45 rotatably mounted on a post 47 which is rigid with the head of the machine and extends obliquely downward (Fig. 2), the sleeve and plate being held from slipping off the bottom of the post by a round rabbeted plate 49 fastened to the bottom of the post 47 by screws, one of which is shown at 51. As shown in Fig. 2, the post 47 is received in a bore in the head of the machine and is held rigidly in place by a draw-bolt 52. With this construction, the jack can slide lengthwise on the plate 43; and the jack, the plate and the sleeve can rotate as a whole about the post 47. Extending downward through the post 47 is a hollow shaft 53 eccentric to the post and having fast to its lower end the pinion 55 which meshes with the teeth of the rack formed on the jack, the diameter of the pinion being less than the distance between the side walls 23 of the jack. This hollow shaft (Figs. 1 and 2) has fast to its upper end a bevel gear 57 meshing with a small bevel gear 59 on the upper end of an upright shaft 61 which is rotated first in one direction, then in another, and finally brought to rest in a manner which will be described later. Returning now to Fig. 6, and assuming that the pinion 55 is rotating in a counterclockwise direction, the jack will be swung 90° counterclockwise until the heel member 29 strikes the rail 37. It will then slide along the rail (as shown in Fig. 7) until the inner curved face of the member 29 engages the sleeve 45 whereupon no further straight-line sliding movement can take place. The jack will then rotate counterclockwise through 180° until the contact member 33 strikes the rail 37. This alternating movement of rotation and translation will continue as long as the pinion 55 rotates in a counterclockwise direction. By referring to Fig. 7, it will be noted that the guide-rail 37 has bent ends, one of which is shown, having slots through which pass screws, one of which is shown at 63. These screws are threaded into the head of the machine, and the ends of the rail 37 are slidable upon them. The ends of the rail are supported by coiled springs 67 located between the rail and the head of the machine so as to cushion the blows, so to speak, of the jack when it has been rotated through 180° and one or the other of its members 29, 33 strikes the guide-rail. It has been explained above that when the jack is moved forward until the cementing operation has been completed, its motion is reversed so as to return it to initial position. Referring to Fig. 2, this reversal is brought about by pulling up a link 69 which is connected with mechanism in the base of the machine, said mechanism acting to reverse the direction of rotation of the shaft 61. The upper end of the link 69 is pivoted to the outer end of a small arm 71 the hub of which is loose on a stub-shaft 13. A second small arm 75, the hub of which is also loose on this shaft, engages with its outer end a small block 77 slidable in a guide-way in the head of the machine and urged upwardly by a small compression spring 79. The

slide block 77 lies in the path of movement of a cam 81 (Figs. 6 and 7) which may be fastened to the jack in various adjusted positions. As thus far described, the small arms 71, 75 are not connected, and consequently pushing down of the slide block by the cam 81 would merely rock the arm 75. It will be noted that the cam 81 will pass the small block 77 more than once during the forward movement of the jack because the jack makes more than one complete rotation or cycle. It is necessary, therefore, that the arms 71, 75 shall only be interconnected after the cam 81 has passed the block 77 once during the forward cycle. In order to connect the arms 71, 75 at times so that rocking the arm 75 in a counterclockwise direction will rock the arm 71 and thereby pull up the link 69, there is rotatably mounted on a pin 83 carried by the arm 71 a depending latch 85 which is urged continually by a coiled torsion spring 87 to swing away from the observer, as viewed in Fig. 2, and beneath the lower edge of the small arm 75 in which position any counterclockwise swinging movement imparted to the arm 75 will also be imparted to the arm 71. In the position of parts shown, the latch 85 is not beneath the arm 75 first because said arm is being held down partly past the latch 85 against the force of the spring 79 by a small projection 89 on a control arm 91 (Figs. 2 and 7) which is pivoted about a pin 93 carried by the head of the machine, and second because the latch 85 is being held out of line with the arm 75 against the force of the torsion spring 87 by a finger 91' formed on the extremity of the arm 91. This arm 91, best shown in Fig. 7, is semi-circular and has near its outer free end the projection 89 referred to above and at its extreme outer end the finger 91' which is holding the latch 85 (Fig. 2) out toward the observer in opposition to the coiled torsion spring 87. A coiled tension spring 88 (Fig. 7), attached at one end to the arm 91 and at the other to the head of the machine, urges the arm to swing at all times clockwise around its pivot 93, as viewed in Fig. 7, into the position shown, so as to render the latch 85 inoperative. With the parts in this position, movement of the jack causing the cam 81 carried by it to engage and push down the small slide block 77 would then merely rock the small arm 75 but would impart no movement to the link 69 and would consequently cause no reversal of movement of the jack. In order to permit the latch 85 to become effective at the proper time to connect the small arms 75, 71, there is mounted on the rotary sleeve 45 a cam 95 (Figs. 6 and 7). When the sleeve 45 is rotated through 180° , the cam 95, which is fast to it, is also moved through 180° , and during this movement it engages a raised cam surface 80 (Fig. 7) on the inner face of the semi-circular control arm 91 and swings that arm temporarily counterclockwise as viewed in that figure. This swinging movement withdraws the projection 89 on the lever from engagement with the small arm 75 (Fig. 2) thereby permitting the spring 79 to slide the block 77 nearer to the sleeve 45, and at the same time withdraws the finger 91' at the extremity of the control arm 91 from the latch 85 whereupon the latch swings beneath the small arm 75. The semi-circular control arm 91 cannot return to the position shown, after the cam 95 has passed the cam surface 80 on the lever, because the small arm 75 is then in the path of movement of the control arm. The small arms 75, 71 are thus held connected so that when later the cam 81 (Fig. 7), moving with the jack, en-

gages and pushes down the slide block 77, the link 69 is pulled up; and this upward pull of the link, as has been explained, starts a second half-revolution of a control cam 757 (Fig. 18) which puts 5 into operation mechanism including a link 765 and a shifting lever 722 for reversing the movement of the jack, all as described later in the specification under the heading "The starting, stopping and driving mechanism." It should be 10 noted that when the cam 81 in its travel with the jack pushes down the slide block 77, the arm 75 is pushed down so that presently the projection 89 on the control arm 91 is no longer in engagement with the adjacent face of said arm 75, 15 whereupon the tension spring 88 swings the control arm 91 back into the position shown to disconnect once more the small arms 75, 71.

Referring now to Figs. 6 and 7, the forward and reverse movement of the jack, with the machine adjusted as shown will be described. In Fig. 6 the jack is in its position of rest with its longitudinal axis perpendicular to the guide rail 37 and its toe-guiding member 33 in contact with the guide rail. It swings 90° counterclockwise until the heel-guide member 29 strikes the guide rail. At this time the cam 95 has been moved 90° from its position shown in Fig. 6 to its position shown in Fig. 7. The jack moves toe foremost along the rail, in the direction indicated by the arrow in Fig. 7, until the heel-guide member 29 fits around the sleeve 45. It then swings counterclockwise, as viewed in that figure, 180° until the toe-guide member 33 again contacts with the guide rail. During this swinging movement, the cam 95 on the sleeve 45 also moves through 180°, and during this movement first engages the cam surface 89 on the control arm 91 and swings said arm to the right thereby causing the two small arms 75, 71 (Fig. 2) to be connected in the manner described above, so that when the cam 95 and sleeve 45 have completed their movement of 180°, the slide block 77, the two small arms 75, 71 and their associated parts are in such positions that depression of the slide block 77 will pull up the link 69. At this time the jack occupies one of its extreme positions, with the toe end of the jack in its extreme position at the bottom of the sheet of drawings, as viewed in Fig. 7, and the cam 81 adjacent to the 40 guide rail 37. The jack now moves in a straight-line path in the direction of the arrow; and, near the end of this movement, the cam 81 passes by and depresses the small slide block 77 (Fig. 2) thereby pulling up the link 69 and starting the mechanism for reversing the movement of the jack. This mechanism, however, does not effect the reversal of the jack for a considerable interval necessary for a half-revolution of the cam 757 (Fig. 18) as later described. During this 50 interval the jack continues its forward movement (with the arrow as viewed in Fig. 7) until the toe-guide member 33 engages the sleeve 45. It then rotates counterclockwise through more than 90° (in the present instance through about 135°) when its movement is reversed and it swings back (through about 45°) and comes to rest in the 55 position shown in Fig. 6 with the toe-guide member 33 in contact with the guide rail 37 and the longitudinal axis of the jack perpendicular to said rail. Just before the reversal of movement of the jack takes place, the cementing tool, which has been in contact with the shoe during the forward movement, is withdrawn from the shoe. 60

75 The movement of a shoe from initial position

to the final position of forward movement is shown in Figs. 33 to 35. Fig. 33 shows the initial position. In Fig. 34, the jack has rotated 90° and is moving to the left. This corresponds roughly to the position shown in Fig. 7. In Fig. 35 it has rotated another 90°, this time about the heel end of the jack. It will continue this rotary movement through another 90°, will then move to the left, heel end foremost, then rotate about the toe end 135° to the position shown in Fig. 36. 10 This is the end of the forward movement. The reverse movement will rotate it backwards through 45° when it will come to rest in the initial position shown in Fig. 1. Inasmuch as, during the latter part of its forward movement, 15 the jack moves past its initial position, the tool applies a coating of cement a fraction more than once around the foxing area so that there is an overlap which depends upon the extent of the reverse movement which is imparted to the jack, 20 it being understood that with a different extent of reverse movement of the jack, its initial position would be changed. As will be explained below, the machine is provided with means for varying the extent of the reverse movement of 25 the jack and consequently for varying the extent of the overlap. With the machine as adjusted and described above, the reverse movement of the jack was a movement of rotation through 45°, and the overlap was of small extent and located 30 at one side of the toe portion of the shoe. If now the reverse movement has been caused to extend through 90° for example, the overlap would have been increased, and the initial and stopping position of the jack would have been 35 45° from the initial position shown in Figs. 6 and 33. The starting position will also depend upon the location of the cam 81, for any fixed setting of the overlap mechanism, because it is this cam 40 81 which initiates the movement of a control cam 757 and, thus, ultimately starts the reverse movement. This reverse movement may of course be caused to take place through the straight-line movement as well as the rotative movement of 45 the jack. The overlaps described above are located at or near the toe end of the shoe. If it is desired to place the overlap at or near the heel end of the shoe, it will be necessary to fasten the cam 81 (Figs. 6 and 7) in a selected position 50 near the heel end of the jack, and in some instances it may be necessary to change the position of the cam 95 which is carried by the sleeve 45. Thus the extent of the overlap and its location on the shoe may be varied. It is also possible to cause the coating of cement to extend once around the shoe so that the ends of the coatings meet without overlapping or even to cause the coating to extend only part way around the shoe so that a portion of the foxing area is not 55 coated. When the operation being performed on the shoe is the operation of cementing the foxing area, the machine is commonly adjusted as herein shown to produce a small overlap; but the cement-applying mechanism may be replaced by 60 other mechanisms (not shown), for example by a mechanism for applying a strip of unvulcanized rubber, known as a foxing, to the foxing area; and in this particular case the overlap is considerable, may amount to several inches and may 65 be located either around the toe end or around the heel end of the shoe or in some other selected locality.

70 It has been explained that, when the machine comes to rest, the shoe-holding mechanism of the 75

jack is in unlocked position. Referring more particularly to Figs. 4 and 5, this shoe-holding mechanism will be described. A toe piece 97 of usual form, the stem of which is adjustably fastened by a cap-screw 99 to a bracket 98 which is rigid with the block 34 and hence the adjustable toe member 33 of the jack, engages the toe portion of the lasted shoe. The last 200, herein illustrated, is of a particular kind used in the manufacture of rubber shoes, that is, shoes some parts of which contain or are made of rubber, such shoes being subjected to a vulcanizing operation after they are otherwise completed. The last is a hollow metal last having an opening 101 in its cone of considerably greater extent than that of the usual last-pin hole of a wooden last. Inasmuch, however, as this opening 101 corresponds to the last-pin hole, it will be termed for convenience a "last-pin hole," and the member 103 which enters it will be termed a "last pin." The last-pin hole 101 has vertical end walls, and the last pin 103 has, formed on opposite edges, teeth 105' which lie close to said walls when the last pin is caused to enter the last-pin hole. The last pin 103 is adjustably fastened to a small rock-shaft 105 mounted in the lower end of a bracket 107, U-shaped in cross-section, which is adjustably clamped by a screw 109 to an open-sided post 111, said post being fastened to and depending from the heel end of the base of the jack. The small rock-shaft 105 (Fig. 5a) has at one end a slotted head to receive a screw-driver and at the other end a split collar 113 clamped to the shaft by a pinch-screw 115. The last pin 103 has a split hub to receive the rock-shaft and is fastened to said shaft by a pinch-screw 117. A coiled torsion spring 119 coiled about one end of the shaft 105 has one end fastened to the slotted head and the other to a pin on the bracket 107; and the collar 113 is adapted to be held against a pin 121 (Fig. 4) on the bracket by the force of the spring. When the pinch-bolts 115, 117 are loosened, the shaft can be turned to wind up the spring and give it the desired tension, after which the pinch-bolts may be again tightened. Thus the tension of the spring may be varied when desired, and the last pin 103 may be adjusted along the shaft 105. Its angular position remains unchanged during this longitudinal adjustment because the rear face of the split hub of the last pin 103 engages a straight flat face 123 (Fig. 5) formed on the bracket 107, said flat face being parallel to the axis of the rock-shaft 105. If now a lasted shoe is presented to the jack as shown in Figs. 4 and 5 and held in this position, pushing the shoe to the right will swing the last pin slightly counter clockwise about the axis of the rock-shaft 105 and will cause the pin to be cramped in the last-pin hole 101 so as to lock the shoe to the jack.

This movement of the shoe to the right is brought about by a clamp 124 which is curved in horizontal cross-section and is provided on its inner face with a felt pad so as not to mar the shoe upper. This clamp has a split hub 123 fastened by a pinch-bolt 125 to the lower end of a pin 127 the upper end of which is fastened by a tapered pin 129 in a socket in a depending portion of a channeled link or bar 131 which is U-shaped in cross-section and is pivoted at one end at 133 to the substantially vertical depending arm of a bell-crank lever 135 and at the other end to the substantially vertical depending arm of a second bell-crank lever 137. The bell-crank lever 135 is pivoted at 139 to the hollow or open-

sided post 111 into which the depending portion at the left-hand end of the link 131 extends, and the bell-crank lever 137 is pivoted at 141 to the block 25 fastened to the base of the toe end of the jack. The substantially horizontal arms of the bell-crank levers are connected by a channeled link or bar 143 which is of inverted U-shape in cross-section and is of a size to be received or telescoped within the U of the lower link 131. A tension spring 145, connected at its left-hand end 101 to a pin carried by the link 131 and at its right-hand end to a pin 147 carried by the block 25 of the jack, urges the bell-crank levers at all times to rock in a counterclockwise direction so as to move the clamp 124 in a straight-line path to 151 the right, thereby forcing the toe portion of the shoe against the toe piece 97 and locking the shoe unit, comprising a shoe on a last, to the jack by clamping the heel and causing the last pin 103 to be cramped in the last-pin hole 101. 200 The spring 145, it will be noted, is substantially enclosed within the U-shaped links or bars 131, 143, one of which extends into or telescopes with the other. In the position of the parts as shown, the tension spring 145 is ineffective because of the 25 position of a push rod 149 which has pushed down the link 143, thereby rocking the two bell-crank levers clockwise into the position shown, and moved the clamp 124 into its extreme left-hand position. When a shoe is presented to the jack in the position shown in Figs. 4 and 5 and the treadle of the machine is depressed, the rod 149 is pulled up whereupon the tension spring 145 rocks the bell-crank levers 135 and 137 and moves the lasted shoe to the right to push it against the toe piece 30 35 and to lock it to the jack. The push rod 149 passes loosely through the shaft 53, not far from the center of the jack-supporting post 41, and, regardless of the position of the jack, is always in alignment with the bar 143 so that no matter 40 when the rod is depressed, it will be effective to release the shoe.

Referring to Figs. 1 and 2, the upper end of the push-rod or release pin 149, above the top of the hollow shaft 53, has pinned to it at its 45 upper end a block 151 having a flat upper end pivoted at 153 to the middle of a lever 155, one end of which is pivoted at 157 to a bracket which is rigid with the head of the machine, and the other end of which is pivoted at 159 to the 50 upper end of a multi-part telescopic pull-rod, shown in detail in Fig. 10, containing a spring in which, as will presently be described, energy is stored to move the shoe clamp to unlock the shoe at the end of the cementing operation. 55 This telescopic rod comprises an upper rod 161 threaded into a block 163 having a split upper end to receive a pinch-bolt 164 to hold the rod in adjusted position in the block. The lower end of this block is threaded into a sleeve 165 having threaded into its lower end a nut 166 provided with a central bore. Extending up through this bore is a lower rod 167 having at its upper end two nuts 168, and between the lower one of these nuts and the nut 166 is a heavy coiled spring 168' which is normally under some compression and acts, when permitted to do so, to push down the rod 167 into the position shown, there being on the top of the upper nut 168 a fibre washer which is held against the end face 70 of the block 163. The coiled spring is considerably stronger than the tension spring 145 (Fig. 5), which acts when permitted to do so to move the clamp 124 to the right to lock the shoe to the jack, and is very much stronger than said 75

spring 145 when it is put under increased compression in a manner presently to be described so as to store up more energy in it. The lower rod 167 is pivoted at 169 (Fig. 3) to the outer end of a lever 170 which is rocked up and down, in a manner to be described, at the proper times, said lever having at its outer end a hardened plate 171 which is in engagement with a hardened block 172 of a catch, in the form of a substantially vertical rock-arm 173, when the parts of the machine are in the position shown in which the push-rod 149 is being held down and the shoe is not locked to the jack. When a treadle 131 (Fig. 11) of the machine is depressed, the first effect of such depression is to swing the catch 173 to the right, as viewed in Figure 3, to release the lever 170. This lever, at this time, is free to be swung up, and nothing then holds down the lever 155 (Figs. 1 and 2) to which the upper end of the push rod 149 is pivoted. Indeed, the lever 155, during all the time that it is being held down, is being urged upwardly by a spring-pressed plunger 174 acted upon by a coiled compression spring 175 located in a socket in a rigid part of the head C of the machine. As soon then as the downward pull on the telescoping rods 167, 165, 161 ceases, the spring 175 lifts the arm 155 and pulls up the push rod 149 whereupon the tension spring 145 (Fig. 5) locks the shoe to the jack.

During the subsequent movement of the jack a stop in the form of a finger 177 (Fig. 2) is swung beneath the lever 155 so that the lever can not again be pulled down while this stop remains in position. The hub of the finger 177 is fast to a small rock-shaft 178, and has integral with it a second finger 179 which is acted upon by a compression spring 181 mounted between this second finger and a rigid part of the head of the machine to swing the stop finger 177 beneath the lever 155 when permitted to do so. Fast to this rock-shaft 178 is an arm 183 to which is pivoted the upper end of a long link 184 the lower end of which (Fig. 3) is pivoted to the outer end of a rock-arm 187. This arm is connected to mechanism in the base of the machine which, after the forward and reverse movements of the jack have been completed, brings the jack to rest. Just as the jack is brought to rest, the link 184 is pulled down to withdraw the finger-stop 177 from beneath the lever 155. Meantime, the rod 167 (Fig. 3) has been pulled down by the lever 170 so that the spring 168 in the sleeve 165 is under considerable tension; and the end of the lever has been engaged once more by the catch 173. Consequently, when the finger 177 is pulled from beneath the lever 155, this lever is pulled down into the position shown, and the push rod 149 (Fig. 5) pushes down the link 143, as shown in Figure 5, to unlock the shoe.

Referring to Figure 2, it has been explained that the hollow shaft 53, which carries at its lower end the pinion 55 for driving the jack, carries at its upper end a bevel gear 57 which is driven from the upright shaft 61 and that the lever 155 is moved down just as the jack is brought to rest. In order to ensure that the bevel gear 57 shall not overrun when power is withdrawn from the upright shaft 61, a friction drag member 191 engages the top of the bevel gear 57, said member being prevented from turning by a pin 193 carried by the stationary head of the machine and being urged against the bevel gear by light compression springs 195. This drag member has a hollow upwardly extending

stem extending through a bore in a portion of the head. Through this hollow stem the push rod 149 extends so that, when the lever 155 is pulled down into the position shown to unlock the shoe from the jack, just as the jack comes to rest, the block 151 on the upper end of the push rod 149 pushes down the hollow stem of the drag member 191 to push said member strongly against the bevel gear 57 and thereby prevent its overrunning, and also to retain the jack in the position in which it comes to rest. Since the jack is mounted in an inclined position, it would otherwise slide or rotate, when released, under the action of gravity and the jack would not be in the usual position to receive the next shoe.

The foxing cementing mechanism

Referring first to Figs. 23, 24 and 24^a, the cement-applying tool, indicated as a whole at 201, has a concave face 202 which contacts with the foxing area of the shoe when in operative relation, as shown, to a shoe 100 which is held by the jack and moved during the cementing operation in a manner which has been described above. This tool comprises a small thin base 203 having a cavity therein closed by a cover plate 204 which is fastened to the base by screws 205. Into this cavity or compartment cement is forced under pressure through a pipe 206, one end of which registers with a hole in one wall of the tool, and is forced out through a plurality of small grooves or channels 207 located in a wall of the cavity beneath one edge of the cover plate 204. As will be noted from Fig. 24^a, the concave face 202 of the base 203 in which the cavity is formed is provided with a rounded outer edge or ridge 203' which drags along the surface of the shoe. The channels 207 are formed at one side of this ridge so that the outer ends of these channels are never closed by contact with the shoe. They are on the leaving side of the tool so that the coat of cement is not disturbed by the contact of the rounded edge of the base 203 with the foxing area of the shoe. Having chosen the desired cross-sectional area of the outlet opening in accordance with the viscosity of the cement, the pressure employed and other factors, it is found desirable to subdivide the outlet opening into a plurality of 50 grooves or channels instead of using a single slot, thereby permitting each of these grooves to be deeper while maintaining the same total cross-sectional area of the outlet openings. This arrangement, with its deeper grooves, thereby tends to avoid any plugging of the openings by small particles of solid matter in the cement. The area chosen is that which maintains the desired pressure at the outlet of the nozzle such that cement will be pushed rather forcibly against the shoe but without being driven under a pressure great enough to cause spattering or spouting of the cement in undesired directions. At the upper end of the concave face 202 the tool is provided with a guard plate 204' which closely approaches but does not actually contact with the shoe and which serves to limit the upward flow of cement so that there will be no soiling of the shoe above the upper edge of the foxing area. Friction between the tool and the shoe is minimized by the provision of a thin disk-like roll 213 the edge of which rides upon the shoe substantially at the upper edge of the foxing area (Figs. 24 and 37). As a result of this arrangement of the cement-applying tool, the cement

is forced out in a series of streams which merge and become a single stream flowing directly against the foxing area of the shoe, the distance between the outlet ends of the grooves or channels 207 and the surface of the shoe being so small that there is practically no space for the cement to jump, and the danger of "holidays" or uncoated portions is eliminated. An excess of cement is delivered to the shoe and any unused 10 cement drains off and is caught and used again as will be later described.

Integral with the base of the tool are two ears 208 with hooked ends (Fig. 22) and each having a ball bearing roll 209 which runs in a segmental track formed in a segmental channeled member 210. This channeled member 210 has a thin cover plate 210' leaving only a narrow slit at the rear to admit the hooked ends of the ears 208 while avoiding clogging by cement. Fastened 20 by a bolt 211 to the upper part of the base 203 of the cement-applying tool is a bracket 212 having rotatably mounted on it the small roll 213, the central point, indicated at *x*, at the right hand of the roll as viewed in Fig. 24, where it contacts with the shoe, being located on an axis which contains the center of curvature of the track in the segmental member 210 so that this point remains stationary with respect to the member 210 when the rolls 209 of the cement-applying tool travel in the segmental track, and the cement-applying tool swings angularly. The upper end of the segmental track is closed by a plate 214, and the lower end is closed by a plate 215 to prevent surplus cement, which is forced continuously through the grooves 207, from getting into the track. Through the lower plate 215 is threaded a stop-screw 216 which limits the clockwise rotation of the tool (Fig. 24), said tool being urged continually, by a mechanism to be described later, to rotate in a clockwise direction so as to hold the concave face 202 of the tool against the foxing area of the shoe, it occupying sometimes positions such as shown in Fig. 37 where it engages the forepart, and at other times positions such as shown in Fig. 24 where it swings under an undercut shank portion. Fastened to the bracket 212 by a small screw is a scraper 217 for cleaning cement from the periphery and top of the roll 213. As will be described later, the segmental member 210 is mounted for yielding movement widthwise or radially of the shoe so as to follow the contour of the foxing area as well as for yielding movement heightwise of the shoe so as to follow the rise 55 and fall of the foxing area lengthwise of the shoe, the heightwise relation being determined by contact of the shoe bottom with a bottom rest 218. As the shoe is moved by the jack in the manner which has been described above, the cement-applying tool follows the foxing area of the shoe and is held at all times against said area by yielding means to be described later.

Referring now to Fig. 22, the bottom rest 218 is hollowed out on its under side near its forward edge and is pivoted on a pin 219 carried at the outer end of a bracket 220 adjustably fastened by a screw bolt 221 to the outer bent end of a tool-carrying arm 222. A leaf spring 223, fastened near its middle to the under side of the bracket 220, contacts with its extremities the under side of the bottom rest 218 to hold said rest normally balanced about the pin 219 while permitting said rest to rock. The rest is inclined with respect to the plane of the bottom of the shoe (see Fig. 24) to facilitate bringing the tool

into engagement with the shoe. The mounting of the bottom plate is also shown in Fig. 21. Referring now to the last-named figure, the cement-applying tool and the shoe bottom rest are held above an inclined catch basin or drain board 226 having a strainer 224 in its middle portion. The cement which drips from the shoe (or which flows from the cement applying tool when no shoe is present) is caught, strained and returned to a cement supply tank which will be 10 described later.

The segmental member 210 (Fig. 22), which carries the cement-applying tool, is fastened by screws 225 to a flange which is integral with the arm 222. In the position of parts shown in Fig. 15 22, this arm is holding the cement-applying tool away from its operative position and somewhat below this position; and when a shoe is presented to the jack and locked, this arm will swing up somewhat as well as toward the shoe so that the cement-applying tool will be moved obliquely upward with respect to the bottom of the shoe into contact with the shoe as shown in Fig. 37. The inclined bottom rest 218 contacts first beneath the toe end of the shoe and brings the 25 tool into contact just at the desired level. This arm is so mounted that, during the cement-applying operation, its outer tool-carrying end may move yieldingly widthwise of the shoe and heightwise of the shoe to permit the tool to follow the 30 foxing area as has been described. To this end, the hub of the arm 222 is carried indirectly by a hollow cylindrical yoke 227 which is integral with the upper end of an upwardly extending rock-shaft 229, said rock-shaft being actuated in 35 a manner presently to be described to swing the arm 222 toward the shoe just before the cementing operation begins, to hold the cement-applying tool and the shoe bottom rest in contact with the shoe during the cementing operation, and 40 finally to withdraw the tool and bottom rest from the shoe at the end of the cementing operation. An elongated hub 222' at the right end of the arm 222 is fastened by a set-screw 231 to a small rock-shaft 233 which passes through a bore 45 in this hub. Near its inner end the small shaft 233 passes through a roller bearing 235 carried at the inner end of the yoke 227 and held in place by a washer 236. Near its outer end, the small shaft 233 passes through another roller bearing 50 237 carried indirectly by the yoke 227, said last-named bearing being carried by a sleeve 239 which fits into the outer end of the yoke and is held in lengthwise and in angular adjustment by a pinch-screw 241 which clamps the split 55 outer end of the yoke to the sleeve. A torsion spring 243, fast at one end to the sleeve 239, and at the other end to the hub of the arm 222, tends at all times to swing the arm upward so that, during the cementing operation, the bottom 60 rest 218 will be held in contact with the bottom of the shoe. The outer tool-carrying end of the arm 222, in the position of rest of the machine shown in Fig. 22, is held depressed below the inclined plane of the bottom of the shoe, as the 65 shoe is held in the jack, by mechanism which will be described later. When the pinch-screw 241 has been loosened, the sleeve 239 may be turned angularly to wind up the spring 243 to a proper tension and may also be adjusted longitudinally to locate properly the roller bearing 237 at one end of the shaft 233 about which the hub 70 of the arm 222 swings.

Fastened to the inner end of the small shaft 233 by a pinch-bolt 245 (Figs. 21, 22) is a collar 75

247 carrying a roller bearing 249 in which is rotatably mounted one end of the small pipe 206 through which cement is forced into the cement-applying tool, the left-hand end of this pipe having fast to it a collar 251 provided with flanges (Fig. 24) which are attached by screws 253 to a wall of the cement-applying tool. The right-hand end of the pipe 206 has fastened to it by a pinch-bolt 255 a split sleeve 257 having at its right-hand end a portion of reduced diameter provided with perforations 259; and upon this reduced portion is rotatably mounted a coupling 261. Between the right-hand end of the sleeve 257 and the left-hand end of the coupling 261 is a washer 263, the coupling 261 being held against the washer at all times by a compression spring 265 located between the head of a bolt 267 and the right-hand end wall of the reduced portion of the sleeve 257. The bolt is slideable through a bore in this end wall and is threaded through the end wall of the coupling 261, being locked in adjusted position by a nut 269. The coupling 261 is thus held from longitudinal movement with respect to the sleeve 257 but is permitted to swing angularly on the sleeve. A supply pipe 271 leads into the coupling 261, and through this pipe is forced cement which passes through the holes 259 into the sleeve 257, thence through the pipe 206 into the cement-applying tool 201 and finally out through the grooves 207 (Figs. 24 and 24a). The purpose of mounting the coupling in the manner described above is to permit angular movement of the pipe 206 in its roller bearing 249 as the tool 201 moves angularly in the track 35 of the segmental member 210 to maintain contact with the shoe.

The pipe 206 (Fig. 22) is bent as shown in such manner that the axis of rotation of the right-hand end of the pipe in the roller-bearing 249 is in line with the point on the periphery of the small roll 213 of the cement-applying tool which at any given moment is in engagement with the shoe. This point is the one indicated at *x* in Figure 24 and is located, as has been stated, on a line which contains the center of curvature of the segmental guide member 210 and coincides substantially with the upper edge of the foxing area. A tension spring 273 (Figs. 1, 21 and 22), fast at one end to an ear on the sleeve 257 and at the other to a pin on the yoke 227, tends at all times to rock the cement-applying tool, counterclockwise as viewed in Figure 24, as far as the stop-screw 216 will permit. This stop-screw, however, is effective only in the position of rest 55 on the machine. When a shoe is in operative relation to the tool, as shown in Fig. 24, the tool is in a position in which the roller 209 is spaced more or less from the screw 216. In such case, although the tool is free to swing clockwise (Fig. 24) when the contour of the foxing area of the moving shoe necessitates such swinging movement, it is being urged at all times to rotate counterclockwise by the tension spring 273 so as to hold the curved shoe-engaging portion of the 60 tool against the shoe as the contour of the foxing area changes. As has been stated, the tool-carrying arm 222 may swing in two paths during the cementing operation; but with the construction described above in which the pipe 206 and 65 the cement-applying tool 201 are both carried indirectly by this arm, the tool may always swing about the point *x* irrespective of the position of the arm 222.

Inasmuch as the jack holds the shoe initially 75 in an inclined position with the longitudinal axis

of the shoe (Fig. 1) extending upward to the left and downward to the right at an angle 45° to the horizontal, the upwardly extending rock-shaft 229 (Figs. 21, 22) is located at right angles to the longitudinal axis of the shoe so that, if the tool-carrying arm 222 were rigid with the rock-shaft 229 which carries the yoke 227, the tool-carrying arm 222 would move toward and from the shoe in a path the plane of which would make the same angle with the horizontal as does the longitudinal axis of the shoe. It is desirable, however, that, when the tool-carrying arm is withdrawn from the shoe and returned to the shoe, its path of movement should make with the horizontal an angle a little more abrupt than an angle of 45°. 10 The purpose of providing such a path for the tool and the bottom rest is to cause the tool and rest, when they are moved toward the shoe prior to the beginning of the cementing operation, to move not only toward the shoe from the side or 15 end thereof but upwardly with respect to the shoe so that the bottom rest will seat against the bottom of the shoe with a component of upward movement before the cement-applying tool contacts with the shoe, since by moving the tool and 20 rest in this manner the proper initial angular position of the tool about the point *x* is thus insured. Thus, what may be termed a lowering of the tool-carrying end of the arm 222 occurs when the arm is swung away from the shoe in the position shown in Fig. 22.

This lowering takes place in opposition to the force of the torsion spring 243. To cause such lowering when the tool-carrying end of the arm 222 is swung away from the shoe, the hub of said arm has a tail 275 (Figs. 1 and 22) which is engaged and pushed up at the proper time by an abutment, said abutment including a rod 279 slideable up and down in a bearing formed in a lug 227 which is integral with the yoke 227 (Fig. 1). 40 The outer end of the tail 275 has a downward extension adapted to be engaged by the abutment comprising the head of a screw 277 threaded into the upper end of the small rod 279 having an enlargement at its lower end to which enlargement 45 is pivoted a small cam roll 281, said enlargement being guided in the sliding movement of the rod by a yoke 283. Cooperating with this cam roll 281 is a cam block 285 slidably mounted on the carrier B and held in adjusted position by a butterfly 50 nut 287 threaded on the outer end of a pin 289 threaded into the carrier B and extending through a slot in the block 285. With the parts in the positions shown in Figs. 1 and 22, the tool-carrying end of the arm 222 has been swung 55 away from a shoe which has just been cemented, said movement having taken place about the axis of the upwardly extending shaft 229 (Fig. 22). This movement swung the tail 275 on the arm 222 to the left as viewed in Fig. 1 and caused the cam 60 roll 281 to ride up the inclined surface of a cam block 285 into the position shown, thereby depressing the tool-carrying end of the arm 222 so that the cement-applying tool (or part of it) and the bottom rest 218 are somewhat below the toe 65 end of the shoe, as viewed in Fig. 1, and have also moved down somewhat in a direction parallel to the heightwise axis of the shoe. The tool-carrying arm 222 (Fig. 22) is rocked down about the axis of the small shaft 233 when the arm is 70 withdrawn from the shoe and is rocked upwardly about said axis when the arm is swung back toward the shoe.

The swinging of the tool-carrying arm 222 into and out of operative position is accomplished. 75

as has been stated, by rocking the upwardly extending shaft 229 to the upper end of which the yoke 227 is fast. Referring now to Figs. 21 and 25, the upper end of the rock-shaft 229 is rotatably mounted in bearings in the carrier B and held from downward movement, and the lower end of the shaft passes through a ball bearing 291 mounted in the hub of a heavy cam lever 293 of inverted U-shape in cross section. This hub 10 has an upwardly extending cylindrical projection 295 which is rotatable in a cross-bar 297 rigidly fastened to lugs 297' on the frame, the lower end of the shaft 229 passing freely through the hollow projection 295 of the hub of the cam lever. The ball bearing 291 (Fig. 25) is held in the hub of the lever by a split collar 299 held fast to the bottom of the shaft 229 by a key 301 and a pinch-bolt 303. This collar is connected to the cam lever 293 by a heavy tension spring 305 connected at one end to a lug on the collar and at the other end to a pin 307 near the inner end of the cam lever, the spring, when permitted to do so, holding a stop-screw 311 carried by the hub of the lever against a lug 309 formed on the collar 299. The cam lever has at its inner end a roll 313 running in a cam track 315 on a cam 317 which is provided on its periphery with a gear 319, said gear having imparted to it at proper times half-revolutions by an elongated gear 728 which will be described later. The purpose of making the gear 728 an elongated one is to permit the carrier B of the cement-applying mechanism to be adjusted heightwise of a shoe as has been described without disturbing the mesh 35 of these gears.

Assuming now that the machine is at rest, the operator presents a shoe to the jack and depresses the treadle 737, as has been stated hereinbefore. Depression of this treadle 737 releases the catch 40 173 (Fig. 11) allowing the rod 161, 167 and lever 155 (Fig. 2) to be lifted by the spring plunger 174 thereby raising the push rod 149 and allowing the spring 145 (Fig. 5) to clamp the shoe to the jack. The same treadle motion also starts mechanism 45 to be later described which rotates the cam 317 (Fig. 25) through a half-revolution to swing the cement-applying tool into contact with the shoe, and starts the rotation of the jack. The first part 50 of the half-revolution of the cam 317 causes the rock-shaft 229 to be rotated clockwise (Fig. 25) through the heavy spring 305 which holds the lug 309 in contact with the stop-screw 311. This 55 rocking movement of the shaft 229, which will be counterclockwise, as viewed from above in Fig. 22, swings the cement-applying tool and the shoe bottom rest toward the shoe. This swinging movement continues until the tool and bottom rest contact with the shoe. During the latter part 60 of the half-revolution of the cam 317 (Fig. 25) the shaft 229 can no longer rotate because the cement-applying tool is pressed against the shoe, and consequently the latter part of this half-revolution moves the stop-screw 311 away from the lug 309 so that, during the cementing of the 65 shoe which then takes place, the rock-shaft 229 may rock in both directions when necessary and thus permit the cement-applying tool to follow the contour of the foxing area. At the end of the cementing operation, the cam 317 is caused to make a second half-revolution which withdraws 70 positively the cement-applying tool and the bottom rest from the shoe so that the parts come to rest in the positions shown. It should be noted that by connecting the inner end of the heavy tension spring 305 to the cam lever 293 instead

of to the carrier B, the extra tension to which the spring is subjected during the time that the cement-applying tool is being held against the shoe and the stop-screw 311 and lug 309 are in separated relation is greatly reduced. The spring 5 305 is under an initial normal tension in the position of parts shown. Inasmuch, however, as a very small angular movement of the rock-shaft 229 corresponds to a considerable swinging movement of the cement-applying tool, the extent of 10 any movements of the rock-shaft 229 during the cementing operation is very small, and consequently the increased tension of the spring and its changes in tension are also very small with the result that the cement-applying tool is held 15 against the shoe with a pressure which is substantially uniform in all positions of the shoe.

During the cementing operation the cement-applying tool is free not only to move in and out with reference to the shoe, as has just been described, to follow the contour of the foxing area, but is also free to move up and down heightwise of the shoe to follow the up-and-down curvature of the foxing area from one end to the other of the shoe. This is possible because, when the tool-carrying arm 222 is swung toward and into contact with the shoe, the small roll 281 (Fig. 1) which holds up the tail 275 of the tool-carrying arm in the stopped positions of the machine, runs entirely off from the cam block 295. When the 25 parts are in this position the tool-carrying arm 222 may swing up and down heightwise of the shoe. The spring 243 tends always to raise the tool and the bottom rest 218, the extent to which the tool can thus be raised being limited by contact of the bottom of the shoe with the bottom rest 218. Thus the cement-applying tool is held 30 yieldingly against the shoe and may move in any one or in all of three paths at any time, a path in and out substantially perpendicular to 40 the heightwise axis of the shoe, a path substantially parallel to said heightwise axis, and a path of angular movement the plane of which is substantially perpendicular to the foxing area at the point of engagement of the tool with said 45 area, said path being determined by the cam track in the segmental member 210.

Referring to Fig. 21, the lower end of the pipe 271 which leads into the rotary coupling 261 is connected to one end of a flexible pipe 320, the 50 other end of which is connected to one end of a pipe 321. The other end of the pipe 321 is connected by an elbow 322 through a T-coupling 323 and a nipple 324 (Fig. 26) with the upper portion of a hollow two-part member 325 having 55 a strainer 326 therein. The cement is forced up through a pipe 327 which leads into the lower portion of the member 325, through the strainer 326, up through the nipple 324 and the coupling 323 (Fig. 21), through the pipes 321, 320 and 271 60 into the coupling 261 and thence through the pipe 206 to the cement-applying tool. Connected with the stem of the T-coupling 323 is a relief valve structure, best shown in Figs. 31 and 32, comprising a casing 328 which is connected with 65 the interior of the coupling 323. This casing contains a relief valve 329 held yieldingly against a conical seat by a compression spring 330, the tension of which may be varied by turning an adjusting screw 331. Leading from one side of the 70 casing 328 is a nipple 333 connected with a flexible pipe 335 (Fig. 21) which conducts any cement which is forced past the relief valve back to the cement-supply tank. The relief valve 329 has on its periphery grooves 337 so as to prevent 75

any cement which might work into the space between its outer end and the end of the screw 331 from interfering with the operation of the valve. As will be explained below the cement is forced from the cement-supply tank to the cement-applying tool by means of a rotary pump. When no relief valve is present in the cement-supply line, it has been found that the delivery of cement from the nozzle of the cement-applying tool is not uniform but pulsates more or less. This objectionable phenomenon may possibly occur because the liquid cement is somewhat compressible or may be due to some peculiarity of the action of the pump. At any rate, it exists; and it is because of this irregular delivery of the cement that the relief valve is provided. Any pulsations in the flow of the cement, which would otherwise occur at the nozzle of the cement-applying tool, are taken care of by this relief valve.

Referring again to Fig. 26, it will be seen that the casting which provides the inclined drain boards 226 comprises also a cement supply tank 339 beneath one drain board. This tank has a side cover 339', removable for cleaning, and a drain 339''. The cement-supply tank 339 is filled, for example, to the level of the dotted line 341, by pouring cement upon the inclined drain board 226, said cement passing through the large screen 224 and through a passageway formed between the downwardly turned end of the drain board and a baffle plate 343 which is integral with the upper wall of the cement-supply tank. Thus the cement is exposed to the air of the room only on that portion of its surface which is in the passageway. It will also be clear that the cement which flows from the cement-applying tool and falls upon the screen 224 or the drain board 226 will be returned to the cement supply tank. The pipe 327 which leads with one end into the strainer member 325 in the cement-supply line is connected at its other end by a coupling 345 to the upper end of a pipe 347, the lower end of which leads from the outlet of a gear pump, the inlet of which is indicated at 349. The gears of this pump are indicated at 351, and the rotary shaft of the lower gear at 352. Fast to the right-hand end of this shaft is a collar 353 having spaced holes (Fig. 29) to receive pins 355 carried by a collar 357 (Fig. 30) fast to a shaft 359 to which is also fast a gear 361, said gear meshing with a small driving gear 363 on one end of a shaft 365. The other end of this shaft carries a sprocket driven by a chain 367 from a sprocket driven by a small motor 369 (Fig. 3), said motor being controlled (Fig. 9) through a switch-box 371 projecting from which is a handle 373. The cement pump is driven continuously, while the machine is being used, so that cement is being continually forced through the nozzle of the cement-applying tool whether or not a shoe is being cemented, the surplus cement falling upon the drain board 226 or the large screen 224 and being returned to the cement-supply tank. Referring again to Fig. 26, a bracket 375 which carries the shafts 359 and 365 is fastened to the adjustable head B (Fig. 3) which carries all of the cement-applying mechanism and may be adjusted, as has been explained, up and down in a path which is inclined to the horizontal and is substantially parallel to the heightwise axis of a shoe which is being held in the jack. Referring again to Fig. 26, the chain connection 367 between the sprocket on the shaft 365 and the motor which drives it permits the carrier B to be adjusted as has been de-

scribed. The connection between the shaft 352 of the pump and the driving gear 361, which comprises the pins 355, permits the cement-supply tank to be removed at any time after it has been disconnected from the carrier B by which it is carried. Within the tank is an agitator 376 (Figs. 26 and 27) on a shaft 377 connected to the pump shaft 352.

The toe cap cementing mechanism

It is sometimes desirable to coat with cement not only the foxing area but also the toe portion of the upper of the shoe to which a toe cap is later to be applied, and the present machine is equipped with mechanism for performing this operation if desired, said mechanism being termed for convenience a "toe cap cementing mechanism", since it applies cement to the area upon which the toe cap will later be placed. It will be readily understood that this area will vary in different styles of shoes, it being common to change the curvature of the rear edge of the toe cap, but in every instance the "toe-cap area" will lie above the foxing area, since otherwise there will be no area distinct from the foxing area which may properly be termed a "toe-cap area". Referring to Fig. 21, this mechanism comprises a toe cap cementing tool indicated as a whole at 401 which is mounted to swing about an axis substantially parallel to the heightwise axis of the shoe but is normally held swung back out of the way into the position shown. When a shoe has been presented with its toe portion against the foxing cementing tool 201, locked to the jack and rotated 90° in the forward movement of the jack, it will be sidewise to the observer, as viewed in Fig. 21, and will begin its straight-line movement, toe foremost to the left. The swinging of the jack through these first ninety degrees acts, through mechanism including a cam on the moving jack to cause the toe cap cementing tool 401 to be swung into position above the level of the top of the forepart of the shoe so that, during the time that the shoe moves, toe foremost, to the left, into the position shown in Fig. 34 a curtain of cement is delivered from the concave downwardly directed nozzle of the tool (part of which is indicated at 533) upon the toe portion of the shoe. Presently, when the shoe has moved far enough to the left so that this curtain of cement is falling approximately on the toe cap line, where the rear edge of the toe cap will be, the toe end of the moving shoe encounters a small button 403 and pushes it to the left, whereupon the concave nozzle of the tool 401 first drops or moves down to rest upon the shoe and is then withdrawn into its initial position which is shown in Fig. 21. During this withdrawing movement, which finally takes it out of the path of the moving shoe, the concave nozzle of the cementing tool is dragged over the toe portion of the shoe from the toe cap line forwardly and finally down over the toe end of the shoe, thus wiping and smoothing the coating of cement which was applied just previously to the shoe by the curtain of cement which flowed from the concave nozzle of the toe cap cementing tool. In the position of parts shown in Fig. 34, the concave nozzle of the cementing tool has dropped into the position in which it is in contact with the shoe, and is just about to be swung to the left to accomplish its wiping movement. In Fig. 39, the tool is in the same position, while in Fig. 37, the tool is shown while it is still above and out of contact with the shoe.

The toe cap cementing tool is swung into oper-

ative position over the toe portion of the shoe by the angular movement of a rock-shaft 405 (Fig. 37) rotatably mounted in a bearing 407 in the frame and held from axial movement. This 5 shaft has pinned to it near its upper end a collar 409 having integral with it a segmental rack 411 (Fig. 41) with which meshes a second segmental rack 413 at the outer end of an arm 415 pivoted at 417 to a lug which is rigid with the frame, the 10 arm 415 carrying a roll 420 which is engaged, in a manner presently to be described, by a cam 426 on the moving jack. A spring 419 is connected at one end to a pin 421 on the frame and at the other end to a pin 423 carried by the hub of the 15 arm 415. This spring serves merely to return the rock-shaft 405, and the parts carried by it, to initial and inoperative position after the rock-shaft has been rotated to swing the toe cap cementing tool over the shoe. Pinned to the lower end of 20 the shaft 405 (Fig. 37) is a hub of an arm 425 having a downward extension one face of which engages a spring-pressed buffer 427 (Figs. 40, 41) mounted, as will appear later, in a swinging yoke by which the cementing tool is carried. When, 25 therefore, the rock-shaft 405 and the actuating arm 425 are swung counterclockwise as viewed in Figs. 40 and 41, the cement-applying tool is 30 swung into position above the shoe as shown in Fig. 37. The downward extension of the arm 425 is made long enough so that it will contact with the buffer 427 in any position which that buffer may occupy. Referring to Figs. 1 and 3, which, 35 when placed one above the other, show the whole machine, the head B which carries the toe cap cementing tool, the foxing cementing tool, the cement supply tank, and the parts associated with these parts may be adjusted up and down, as has been explained, in a direction oblique to the horizontal and substantially parallel to the oblique 40 post 47 which carries the jack, such adjustment being made for shoes of different heights. Into whatever position the head B may be adjusted, the downward extension of the arm 425 will always 45 strike the buffer 427 when said arm is swung clockwise (Figs. 40 and 41).

The cam 426 (Fig. 41), which cooperates with the roll 420 to rock the shaft 405, is rigidly fastened to the adjustable toe member 33 of the jack by means of screws 428. It will be recalled that 50 in the initial position of the jack and the shoe (Fig. 33) the toe end of the shoe is in contact with the foxing cementing tool and its small roller 213, and that the first movement of the jack and shoe is a movement of rotation through 90°. The 55 shoe then moves to the left as shown in Fig. 34. During these first ninety degrees of rotation, the cam 426 (Fig. 41) rotates the rock-shaft 405 counterclockwise as viewed from above and, 60 through the arm 425 and the buffer 427 swings the toe cap cementing tool over into position above the level of the toe portion of the shoe as shown in Fig. 37. Consequently, as the shoe moves to the left (Fig. 34), the toe portion moves beneath the cementing tool which is then discharging a curtain of cement. In the position of parts shown in Fig. 34, in which a portion of the toe cap cementing tool is indicated at 533, the toe portion of the shoe has received its coating 65 of cement and the cement tool has dropped down into contact with the shoe and is just about to be swung to the left.

The toe cap cementing tool (Fig. 37) comprises a hollow piece having a hollow arm 429 provided 70 with a passageway 431 for cement, said arm hav-

ing a split end clamped to one end of a pipe 433 by a pinch-bolt 435, the other end of the pipe being clamped in a split bearing at the outer end of the hollow stem of a yoke 437 by a pinch-bolt 439 (Fig. 43). The upper arm of the yoke 437 has a split hub clamped to the upper end of a hollow shaft 441 by a pinch-bolt 443 (Fig. 40); and the lower arm of the yoke 437 has a split hub clamped to the lower end of the hollow shaft 441 by a pinch-bolt 445 (Fig. 37). The lower end of the hollow shaft 441 (Fig. 43) has rotatable on it a coupling 447 the upper end of which is held against a washer located between said upper end and an enlargement 441' by a compression spring 449 which bears at one end 15 against the head of a bolt 451 and at the other end against the bottom end wall of the hollow shaft 441, this bolt passing through the end wall of the coupling 447 and having threaded thereon a nut 453. The hollow shaft communicates with the interior of the coupling through holes 455; and into the interior of the coupling leads a flexible cement-supply pipe (not shown) joined to a pipe shown at 456 in Fig. 9 through which cement is forced continuously from the cement-supply tank. With this construction, cement is forced into the coupling 447, up through the hollow shaft 441 and out through the hollow upper arm and stem of the yoke 437 to the toe cap cementing tool. The hollow shaft 441 (Figs. 42 and 43) is rotatably mounted in a yoke-like head 457 which is integral with one end of a shaft 459 the axle of which is at right angles to the axis of the hollow shaft 441. The shaft 459 has a cylindrical enlargement near one end which is rotatable in a ball bearing 461, and has near the other end a portion of reduced diameter which is rotatable in a second ball bearing 463, said ball bearings being carried, one directly and the other indirectly, by a block 465 fastened by cap-screws 467 to a plate 469 which is rigid with one wall of the cement-supply tank. This block has a bore in one end of which the ball bearing 461 is held and in the other portion of said bore is located a sleeve 471 which holds the other ball bearing 463. The block 465 is split through that portion which is bored, and the ball bearing 461 and the sleeve 471 are held in place by pinch-bolts one of which is shown at 473 in Fig. 37. Returning to Figs. 42 and 43, a small sleeve 475 rotatable on the shaft 459 has integral with one end of it a collar having a slot to receive a small pin 479 driven into the shaft 459, so that rotating the sleeve 475 will rotate the shaft 459. A nut 481 and a washer 483 hold the ball bearings, the sleeve 475 and the shaft 459 in proper relation. A torsion spring 485 having one end fast to the stationary sleeve 471 and the other end fast to the collar which is integral with the sleeve 475, urges the shaft 459 at all times to rotate in the 50 direction indicated by the arrow. The torsion spring 485 may be wound up by first loosening the normally stationary sleeve 471, rotating it, and then fastening it again. The rotation of the shaft by the torsion spring 485 takes place in a 55 clockwise direction (Fig. 37) and tends to swing the hollow shaft 441 clockwise and therefore to swing the toe cap cementing tool down. In the position of parts shown in that figure the tool is being held up because a plunger 487, slidably mounted in the tool-carrying yoke 437, has run up the inclined upper face of a stationary cam 489 which is carried by the stationary block 465. The yoke 437 (Fig. 43) is urged to swing at all 60 times away from the shoe about the axis of the 65 70 75

hollow shaft 441 by a torsion spring 491, the lower end of which is fast to the yoke-like head 451 of the shaft 459 and is fast at its upper end to a split collar 493 fastened to the hollow rock-shaft 441 by a pinch-bolt 495. Extending out from the head 457 (Fig. 42) is an arm 497 having pivoted on its outer end a catch 499 normally held in the position shown by a torsion spring 501 which tends to rotate the catch clockwise as far as a stop face on the hub of the catch and a cooperating face on the arm 497 will permit. In the position of parts shown in Figs. 42 and 43, the yoke 457 which carries the toe cap cementing tool is being held out in its normal inoperative position by the torsion spring 491. When now the arm 425 is swung counterclockwise, in the manner described above, it acts through the buffer 427 to swing the yoke 437 counterclockwise, and presently the catch 499 engages a small hardened plate 503 on the yoke 437 and holds the yoke against the force of the torsion spring 491.

The arm 425 (Fig. 41), it will be recalled, was swung by the engagement of the cam 426 with the roll 420; and when the cam has passed the roll, the tension spring 419 swings the arm 425 into its normal position where it remains until the shoe on the jack has been cemented and removed from the jack and another shoe is being operated upon. In the position of parts shown in Figs. 42 and 43, the plunger 487 is just above the level of the adjacent low locality of the stationary cam 489 over which it projects, being prevented, to avoid undue wear, from resting upon the cam because of a stop-screw 505 (Fig. 37) the head of which is then in contact with the surface of the yoke 457 (Fig. 43) and has prevented further rotation of the yoke 437 about the axis of the shaft 459.

Referring to Figs. 42 and 43, when the actuating arm 425 is swung counterclockwise to swing the tool-carrying yoke 437 until it is engaged and held by the catch 499, the plunger 487 rides up the cam 489 thereby lifting the yoke 437 somewhat against the force of the torsion spring 485 so that, when the yoke 437 has been engaged by the catch 499, the toe cap cementing tool is in the position shown in Fig. 37 somewhat above the level of the toe portion of the shoe. This swinging movement of the yoke 437 also opens a valve 50 in the toe cap cementing tool, by mechanism to be later described, to permit cement to flow through it. The shoe then moves toward the observer (Fig. 37) and presently the curtain of cement discharged by the tool has covered the toe cap portion of the moving shoe. At this time the tool is dropped upon the shoe and then swung back to normal position. The dropping of the yoke 437 is caused by moving the plunger 487 (Figs. 42 and 43) to the right, off the cam 489; and in this same movement, the rear end of the plunger strikes the catch 499 (Fig. 40) and disengages it from the yoke 437 whereupon the torsion spring 491 swings the yoke back to normal inoperative position; and, during this swinging movement, causes the toe cap cementing tool, which is then held down upon the toe portion of the shoe by gravity aided by the spring 485, to wipe over said toe portion. As soon as the yoke 437 has been swung back into the position shown in Figs. 42 and 43, the plunger 487 is moved back to the left over the lower port of the stationary cam 489.

The plunger 487 is moved in the manner described above by a bell-crank lever 507 (Figs. 42 and 43) pivoted at 509 to the outer end of a lug

on the yoke 437, the free end of the longer arm of said lever being located in a slot in the plunger 487. The shorter arm of the lever 507 is forked at its free end, and pivoted in this fork at 511 is one end of a short link 513 the other end of which is pivoted to a lever 515. The inner end of the lever 515 is formed as a yoke the upper and lower arms of which are pivoted respectively about upper and lower alined pivots 517, 519 (Fig. 37) carried by ears on the tool-carrying yoke 437. A tension spring 521 (Fig. 40) connected at one end to a pin driven into the lever 515 and at the other end to a pin driven into the yoke 437 holds a flat surface 523 on the lever against a similar surface on the yoke but permits the lever 515 to be 15 swung away from the yoke to rock the bell-crank lever 507 at the proper times so as to pull the plunger 487 off the cam 489 and cause the rear end of the plunger to disengage the catch 499 (Fig. 42) from the yoke 437. When the yoke 437 and 20 the lever 515 occupy the positions shown in Figs. 42 and 43, the plunger 487 has again been moved over the cam 489. Referring again to Fig. 40 the right-hand end of the lever 515 has a split bearing in which is rigidly held by a pinch-bolt 525 25 the left-hand end of a bent rod 527, forming an extension of the lever 515. The right-hand end of the rod 527 carries the small bumper 493 (Figs. 34 and 37) with which, as has been described above, the toe end of the moving shoe contacts. 30 The pushing of the toe end of the shoe against this bumper swings the rod 527 and the lever 515 clockwise, as viewed in Fig. 40, thereby causing the bell-crank lever 507 to pull the plunger 487 to the right. This movement pulls the plunger 487 off the stationary cam 489 so that the yoke 437 is 35 swung down by the torsion spring 485 (Fig. 42). This same movement also disengages the catch 499 so that the torsion spring 491 (Fig. 43) swings the tool-carrying yoke 437 back into its inoperative position, shown in Figs. 42 and 43. 40

Referring to Figs. 38, 39 and 40, the toe cap cementing tool and the valve controlling the flow of cement will be described. The base of the tool is hollow to provide a chamber for cement; 45 and into this chamber leads the passageway 431, as has been stated. The base of the tool has a segmental slot in its bottom in which is suspended, by a leaf-spring 529 fastened at its ends to the base of the tool by screws 531, a wick 533 circular 50 in cross-section and having wound about it in considerably spaced spirals a small wire 535. Several of the turns of this wire are fastened to the leaf-spring 529 at points indicated at 537 by short pieces of fine wire each of which passes 55 around a turn of the wire 535, through two holes in the leaf-spring 531 and has its ends twisted together. Soldered to the upper surface of the middle of the leaf-spring 531 is the head of a pin 539 slidable in a bore in the base of the tool and 60 having through its upper end a cotter pin 541 to limit the downward movement due to the action of the leaf-spring 529. In order to exert additional pressure on the shoe-engaging member, comprising the wick 533 and the coiled wire 535, 65 a second leaf-spring 543, having a hole to receive loosely the stem of the pin 539, rests with its middle on the head of the pin and with its ends against the bottom of the segment slot in the base of the tool. This spring thus exerts its 70 pressure upon the middle of the shoe-engaging member of the tool. Leading from the compartment in the interior of the tool to one side of the wick 533 are a row of small channels, one of which is shown at 545 in Fig. 38, and through these 75

channels cement is forced past the wick and thence to the toe portion of the shoe. The pressure at which the cement is forced through these holes is great enough to cause the streams to merge into a complete curtain which falls from the curved nozzle at the side thereof toward the toe end of the shoe when the nozzle is in the position shown in Fig. 40. When the tool is dropped into contact with the shoe the coils of the wire 535 ride upon the shoe, as shown in Fig. 39, forming separated spacers to keep the wick away from the surface of the shoe a predetermined distance. If the wick were allowed to contact directly with the shoe, it would wipe off more than the desired amount of the cement and act unevenly throughout its length. With the arrangement used, however, more cement than is actually needed may be forced through the holes of the nozzle on to the shoe and then this surplusage wiped off by the wicking while maintaining a uniform depth or thickness of coating, which depends upon the diameter of the wire 535. If desired, the swinging foxing cementing nozzle 201 may embody a wick with surrounding wire (not shown), just as is employed in the toe cap cementing tool, and located on the leading side of the channels 297 where the cover plate 204 is. If so constructed, the tool would not have the rounded ridge portion 203 of Fig. 24^a but would allow the wire coil around the piece of wicking to press against and ride over the shoe. The flow of cement through the channels 545 is controlled by a slide valve 547 having a hardened plate on its bottom. When the toe cap cementing tool is in its inoperative position, this valve covers the holes 545, having then been moved into a position somewhat to the right of that shown in Fig. 38. It is normally held in this closed position and urged at all times to return to it by tension springs 549 (Fig. 40) connected at their inner ends to the base of the toe cap cementing tool and at their outer ends to the horizontal arms 551 of a cross (Fig. 37) which is fastened to the outer end of the stem 553 of the valve 547 by a pin 557 through vertical arms 555 of the cross. The stem 553 passes through a stuffing box. In order to pull the valve 547 into the position shown in Fig. 38 against the force of the springs 549, two small flat links 559 are pivoted at their outer ends to the pin 557 and at their inner ends respectively to upper and lower arms of a fork 561, said arms at their extremities (Fig. 40) being pivoted on a pin 563 carried by the base of the cementing tool. The stem of the fork 561 is guided by lugs on the tool (Figs. 37, 40) and has an enlarged portion at its left-hand end which contacts with a stationary and adjustable stop-screw 565 (Figs. 21 and 40) when the cementing tool is swung into the operative position shown in Fig. 40, thereby rocking the forked member 561 and pulling the valve into the open position shown in Figs. 33 and 40.

The bottom cementing mechanism

In some instances it is desirable to apply cement to the bottom of the shoe as well as to the foxing area, a device of this kind being shown in Figs. 44 to 47, inclusive. In this device cement is forced into a cement receptacle which is rigid with the bottom rest and then up against the bottom of the shoe. Referring first to Fig. 22, it will be recalled that the bottom rest 218 there shown is supported on a bracket 220 fastened adjustably by a screw-bolt 221 to the outer end of the swinging tool-carrying arm 222. When the bottom of a shoe is to be cemented, the screw-bolt is taken

out, the bracket 220 with its bottom rest is removed, and another bracket and bottom rest is substituted. Referring now to Fig. 45, the screw-bolt 221 and a portion of the swinging arm 222 are shown, a new bracket 601 with a new bottom rest having been substituted for the bracket and bottom rest shown in Fig. 22. The bracket 601 has at its lower end a boss through a bore in which extends a cement-supply pipe 603, and the delivery end of this pipe which protrudes from the boss has fastened to it by a pinch-bolt 605 the split hollow stem of a hollow member 607, said member at its outer end having an open side which is closed by a shoe bottom rest 609 (Fig. 47), there being formed thus a chamber 611 into which cement is forced. A row of ports 612 leads upward from this chamber so as to deliver cement to the bottom of the shoe. Fastened by screws 614 to a depending flange on the hollow member 607 is the base 616 of a brush the tufts or bristles 618 of which wipe and smooth the cement which is applied to the bottom of the shoe through the ports 612.

In addition to the bottom rest 609 there are shown two pairs of auxiliary bottom rests, one pair comprising the heads 613, 615 of screws 617, 619, and the other pair comprising the heads 621, 623 of two screws 625, 627. The screws 617, 625 are threaded into sockets formed in a block 629 which is fast to one end of a small shaft 631 rotatable in a bearing 633 which is rigid with the member 607. The screws 619, 627 are threaded into another block 635 which is fast to the other end of the shaft 631. Pivoted to the block 635 at 637 is a latch 639 the inner end of which is normally held in one or the other of two diametrically opposite slots formed in a boss at one end of the stationary bearing 633, said latch being so held by a compression spring 641. In the position of parts shown, the auxiliary bottom rests 613, 615 are being held in operative positions to engage alternately at times the bottom of the shoe, these two auxiliary rests being in adjusted positions with respect to the blocks into which their stems are threaded so as to be effective when cement is being applied to the foxing area of a right shoe. The purpose of these two auxiliary rests in cooperation with the bottom rest 609 is to locate the upper line of the coating of cement on the foxing area in a predetermined relation to the bottom of the shoe. When a left shoe is being operated upon, the latch 639 is swung out of engagement with the slot in the bearing 633 in which it is shown as being held, the shaft 631 is rotated 180° and the latch is allowed to be moved by the spring 641 into the other slot which is indicated at 643 in Fig. 45. The other pair of auxiliary bottom rests 621, 623 are then in operative position.

Assuming now that the auxiliary bottom rests are in the positions shown in which the pairs 613, 615 are operative, the auxiliary rest 613 engages the bottom of the shoe while cement is being applied to the foxing area along one side of the shoe (the opposite side as viewed in Fig. 44) approximately between the ball line indicated at a and the heel breast line indicated at b, the upper line of the coating of the cement, indicated as a whole at 200, being a substantially straight line between these two localities so that the width of the coating of cement is less at the shank portion of the shoe than at the toe and heel portions. When the toe and heel portions are being cemented, neither of the auxiliary rests 613, 615 contacts with the bottom of the shoe, the shoe at these times being seated upon the bottom rest 75

609 so that the line at the top of a coating of cement in these portions of the shoe is at all points substantially the same distance from the bottom edge of the shoe and follows the curvature of said bottom edge. When the shoe has been swung 180° from the position shown in Fig. 44 and the foxing area in the shank portion of the other side of the shoe is being cemented between the localities *a* and *b*, the auxiliary bottom rest 615 is in engagement with the bottom of the shoe and there is no engagement either by the auxiliary rest 613 or by the rest 609. When a left shoe is being cemented, the auxiliary bottom rests 621, 623 are swung up into operative position. 10
 15 The application of cement to the foxing area in the manner described is substantially the same as that which results when the bottom rest 218 of Fig. 22 is employed, this form of application being one which is frequently desired by shoe manufacturers. If, however, it is desired that the upper line of the coating of cement on the foxing area should be at all points substantially the same distance from the bottom edge of the shoe, the auxiliary bottom rests are screwed down 20
 25 into their sockets until they are wholly inoperative, and the bottom of the shoe then rests at all times upon the bottom rest 609. Although, with the auxiliary bottom rests in the position shown the upper line of the foxing is the one indicated 30 approximately by the line 200, it should be understood that the location of this line between the points *a* and *b* as well as the locations of these points can be changed by adjusting the auxiliary bottom rests into other positions. Whether the 35 bottom rest 609 alone is made use of, or whether the auxiliary bottom rests are also used, the cement which is forced continuously through the pipe 603 passes into the chamber 611 and thence up through the ports 612 to the bottom of the 40 moving shoe and is smoothed over the bottom of the shoe by the brush 618.

The starting, stopping and driving mechanism

Referring to Fig. 11 in which the driving mechanism is shown with the machine at rest and the shoe unlocked from the jack, it will be noted first that in the upper left-hand portion of the figure there is shown in whole or in part several of the controlling members which have been referred to above in connection with the movements imparted to the jack and the cementing tool. The rod 167, which, through its associated spring, has just unlocked the shoe-holding mechanism of the jack and is pivoted to the outer end of the lever 170, is being held down by engagement of the upright arm or latch 173 with the end of the lever 170. The link 69 is in its lowermost position ready, when pulled up in a manner which has been described in connection with Fig. 2, to set 50 into operation the mechanism which reverses the direction of movement of the jack. The link 184 is in its lower position ready, when permitted, to be pulled up by the spring 181 (Fig. 2) to swing the stop-block 177 beneath the lever 155. The 55 upright shaft 61 which drives the jack is stationary. The shaft is a sectional one made so for convenience in assembling the machine but will be referred to as though it were a single member.

Referring now to the driving mechanism, as 60 shown complete in Fig. 11, a driving shaft 701 is mounted for rotating and for endwise sliding movement. This shaft is rotated continuously from a belt 704 and a pulley 703 which is fast to the shaft, its hub being keyed to the shaft and held from longitudinal movement thereon by 65

being clamped between a collar 705 on the shaft and a nut 707 threaded on the shaft. The belt is driven from a motor 706 (Fig. 9) which is started and stopped through a switch 706' and a push-button in a control box 707' at the top of the machine. To the right-hand end of the shaft 701 (Fig. 11) is fastened a friction clutch member 708 adapted to engage at times a friction clutch member 710 integral with a sleeve through which the shaft 701 passes, said sleeve being 10 rotatably mounted in the frame of the machine and having integral with it a bevel gear 711. This bevel gear meshes at all times with a bevel gear 712 fast to the lower end of the upright shaft 61. The driving shaft 701, at its left-hand 15 end, carries indirectly a second friction clutch member 713 slidably mounted on the hub of the pulley 703, attached to the pulley by bolts 714 and normally held with its hub in contact with the heads of the bolts by compression springs 715. 20 The purpose of this mounting of the friction clutch member 713 is to permit the member to yield slightly if necessary when the driving shaft is moved positively to the right to cause the clutch member 713 to engage a clutch member 25 716 formed on a sleeve through which the driving shaft extends and having at its inner end a bevel gear 717 which, like the bevel gear 711, is always in mesh with the bevel gear 712 at the lower end of the upright shaft 61. The driving shaft is 30 moved first to the left and then to the right by a yoke 718 fastened at its lower end to the outer end of a rock-shaft 719. The upwardly extending arms of the yoke 718 are provided with rolls 720 which are located between two collars 721, 35 said collars being fast to the driving shaft. The other end of the rock-shaft 719 has fast to it the lower end of a shifting lever 722 (Figs. 17 and 18). In the operation of the machine, as will be described later, the shifting lever 722 is swung first 40 to the left, as viewed in Fig. 11, to cause the bevel gear 711 to drive the upright shaft 61 in a direction to impart forward movement to the jack. It is then swung to the right to cause the bevel gear 717 to drive the shaft 61 in the opposite 45 direction to impart reverse movement to the jack, and finally the shifting lever 722 is returned to the neutral position shown being held thus by a tension spring 723 (Fig. 18) attached at one end to a pin on the lever and at the other end to a pin in the frame of the machine, the upper end of the shifting lever being held against a latch 759 which will be described later.

The movements of the shifting lever 722 are controlled by a cam on a cam-shaft 724 which 50 is caused to make half-revolutions at proper times, said cam-shaft having fast to it a spiral gear 725 meshing with a small spiral gear 726 on an oblique shaft 727, said oblique shaft also having fast to it an elongated gear 728 which acts, 60 through mechanism which has been described above but is not shown in Fig. 11, to move the cement-applying tool into contact with the shoe just as the movement of the jack begins and later to move the cement-applying tool away from 65 the jack just as the forward movement of the jack ceases. A bevel gear 727' on the oblique shaft 727 meshes with a bevel gear 729 on a counter-shaft 730 having slidably keyed at its left-hand end a hub at the outer end of which 70 is a friction clutch member 731 and at the inner end of which is a friction brake member 732. As shown, the friction brake member 732 is being held against a stationary member, and the friction clutch member 731 is being held out of con- 75

tact with the adjacent vertical face on the outer end of the friction clutch member 709 at the right-hand end of the driving shaft. The common hub of the friction members 731, 732 is 5 engaged and moved, first to the left and then to the right, by two rolls 733 both of which are shown in Fig. 19, carried at the lower ends of the arms of a short fork 734 the hub of which is rotatably mounted on a rod 735. Also integral 10 with this hub is an upwardly extending shifting lever 736 which acts at proper times to shift the friction clutch member 731 and the friction brake 732 first to the left and then to the right (Fig. 11) to rotate the shafts 730, 727 and thus to impart 15 half-revolutions to the cam-shaft 724.

Before going further into the details of the construction, the general mode of operation of the machine will be briefly described. With the parts of the machine in their positions of rest, 20 the operator presents a shoe to the jack in the positions shown in Figs. 1, 4 and 5 and depresses a treadle 737 (Fig. 11). The first part of the downward movement of the treadle swings the friction arm or latch 173 to the left thereby releasing the lever 170 to permit the multipart rod, 25 the lower end of which is the rod 167, to rise, whereby the locking of the shoe to the jack is effected in a manner which has been described above. The latch 173 presently returns to the 30 position shown so that, when later on the outer end of the lever 170 is swung down, it is engaged once more by the latch. The further downward movement of the treadle starts the rotation of the countershaft 730 and the oblique shaft 727, 35 said mechanism imparting a half-revolution to the cam-shaft 724. During this half-revolution the elongated gear 728, through mechanism which has been described above, is caused to move the cementing tool into contact with the shoe, the driving shaft 701 is slid to the left to 40 start the forward rotation of the upright shaft 61, and finally the counter-shaft 730, and with it the oblique shaft 727 and the cam-shaft 724, is brought to rest. The shoe is now locked to the 45 jack, the jack is moving forward, and cement is being applied to the foxing area of the shoe. This cementing operation continues until the cam 81 (Fig. 7) on the forward moving jack pushes down the small slide-block 77 (Fig. 2), 50 thereby pulling up the link 69. Referring again to Fig. 11, pulling up the link 69, the lower end of which is shown, has the same effect as though the treadle 737 were again depressed. Consequently, another half-revolution is imparted to 55 the cam-shaft 724. During this second half-revolution the cement-applying tool is withdrawn from the shoe, the rotation of the upright shaft 61 is reversed to reverse the movement of the jack, and the lever 170 is swung down and engaged once more by the latch 173. Prior to the 60 pulling down of the rod 161, 167, the stop-block 177 (Fig. 2) has been moved beneath the shoe-unlocking lever 155 so that the downward pull of the multipart rod (Fig. 10) is ineffective to swing down this lever. The cementing tool has 65 now been withdrawn from the shoe, and the jack is continuing its reverse movement. This movement continues until the jack has been returned substantially to initial position whereupon the rod 184 (Fig. 2) is pulled down to withdraw the stop-block 177 from beneath the shoe-unlocking lever 155. At about the same time the driving shaft 701 (Fig. 11) is returned to neutral position, and the parts of the machine with the exception of the driving shaft come to rest. 75

Referring now more particularly to Figs. 11, 18, 19 and 20, the cam-shaft 724 and its associated parts will be described. At one side of the gear 725 and rotatable with it and with the cam-shaft 724 is a cam 739 having a cam-track 5 740 in which runs a small roll 741 carried at the upper end of a control arm 742 the hub of which is rotatable on the rod 735. In the position of the parts shown the shifting lever 736 is being held in neutral position by a tension spring 743 10 fast at one end to the lever and at the other end to the frame of the machine, said spring holding an adjustable abutment 744 carried by the shifting lever 736 against a stop 745 pivoted on the control arm 742 and held in the position 15 shown by a small compression spring 747, a face on the lower portion of the hub of the stop 745 engaging at this time a shoulder on the control arm 742 which prevents further rotation of the stop clockwise, as viewed in Fig. 18. The abutment 744 is slidably mounted on the control lever 736 and may be adjusted by turning an adjusting screw 749. The stop 745 has a tail 745', and beneath this tail is the end of a lever 750 which may be swung up about the axis of a rock-shaft 751 to which its hub, and the hub of the latch 173 (Fig. 11), is fast, by pushing up a treadle rod 752 (Fig. 18) the upper end of which is pivoted to the lever. Referring now to Fig. 11, this treadle rod 752 has a vertical slot in its lower end to receive a pin carried at the outer end of the treadle 737 and has also a shoulder against which there is held by a spring 753 the point of a small latch 754 which is pivoted to the treadle. A small horizontal pin 755 carried by the frame 35 lies in the path of upward movement of the tail of the latch. When now the treadle 737 is actuated about its pivot 756, the treadle rod 752 is pushed up and then released. Upward movement of the treadle rod causes the right-hand 40 end of the lever 750, as viewed in Fig. 11, to swing up and engage the tail 745' of the stop 745 so as to disengage this stop from the abutment 744 on the shifting lever 736. The tension spring 743 swings the lever 736 to the right there- 45 by moving the brake 732 and the clutch member 731 to the left. Engagement of the clutch member 731 with the clutch member 709 on the driving shaft 701 starts the rotation of the counter-shaft 730 and, through it, rotation of the oblique 50 shaft 727 and the cam-shaft 724. During a half-revolution of the cam-shaft, the control arm 742 moves first to the right and then to the left. In the right-hand movement the pivoted stop 745 slips over the abutment 744. In its left-hand movement the stop 745 engages the abutment 744 and returns the shifting lever 736 to the in-operative position shown and stops the cam-shaft 724 at the end of the half-revolution. 55

It has been explained that during this first 60 half-revolution of the cam-shaft 724, the driving shaft 701 is moved to the left (Fig. 11) to cause the friction clutch member 709 to engage the friction clutch member 710 and thus start the rotation of the upright shaft 61 to impart 65 forward movement to the jack. It has also been explained that the second half-revolution of the cam-shaft 724 causes the driving shaft 701 to be moved to the right so as to reverse the direction of rotation of the upright shaft 61. Referring more particularly to Figs. 18, 19 and 20, 70 this mechanism will be described in detail. The starting of the rotation of the shaft, 61 and the reversal of its movement are brought about primarily by half-revolutions of a cam 751 which 75

is rigid with the worm gear 725 and the cam-shaft 724. The shifting lever 722 is there shown as in the same neutral position in which it is shown in Fig. 11, being so held by the tension 5 spring 723 which exerts a continuous pull to the right and holds a hardened block 758 which is carried by the forked upper end of the lever 722 against a latch 759 pivoted at 761 to the frame and normally held in the position shown by a 10 small compression spring 762 and an adjustable stop-screw 763 both of which are mounted in the frame of the machine. When this latch is swung upwardly, the spring 723 will swing the shifting lever 722 to the right. There is also a 15 second latch 763 which extends between the arms of a fork at the upper end of the lever 722, said latch being pivoted at 764 to a link 765 having fastened to its right-hand end an elongated block 766 which slides between the arms of the fork 20 at the upper end of the lever 722. This block has a slot through which extends a pin 767 carried by the lever 722. A coiled spring 768 seated in the block holds the outer end of the latch 763 up against a small roll 769 on an arm 770, 25 the hub of which is fast to a small rock-shaft 771. The latch 763 is adapted, when in proper position and when permitted to do so, to swing up into position to engage with the right-hand side of the hardened block 758 so that, when the 30 link 765 has first been moved to the right and the arm 770 which carries the roll 769 has been swung up and thereafter the link 765 is pulled to the left, the shifting lever 722 will be swung into its left-hand position to slide the driving shaft 701 to the left and thereby reverse the direction of rotation of the upright shaft 61 (Fig. 35 11) which drives the jack. In the position of parts shown, the machine has just come to rest due to the fact that the arm 770 (Fig. 18) has 40 been swung down to depress the latch 763, which was holding the shifting lever 722 in its left-hand position, and thereby to disengage this latch from the hardened block 758, whereupon the tension spring 723 has pulled the lever 722 to 45 the right into the neutral position shown. The link 765 has at its left-hand end a roll 772 which runs in a cam-track 773 in the cam 751. The roll 772 and this end of the link 765 are supported upon an arm 773' which is loosely pivoted 50 on the rod 735. During the first half-revolution of the cam, the link 765 is moved to the right and brought to rest. During this movement a trip finger 774, adjustable on the link by means of an adjusting screw 775 and held in 55 adjusted position by a cap-screw 776, swings up the latch 759, whereupon the tension spring 723 pulls the shifting lever 722 to the right thereby sliding the driving shaft 701 to the right and starting the forward movement of the jack. 60 During the same first half-revolution of the cam-shaft 724 the small arm 770 is swung up by mechanism which will be described later, whereupon the latch 763 swings up into a position in which it will engage and swing the shifting lever 722 to the left when the link 765 is pulled to the left during the second half-revolution. Forward movement of the jack continues, and presently the cam 81 (Fig. 7) on the moving jack 65 acts through mechanism which has been described above to pull up the link 69 (Fig. 18) and then to release it. This manipulation of the link 69 produces the same effect, so far as the cam-shaft 724 is concerned, as would be produced by a second depression of the treadle of 70

the machine, namely it imparts a second half-revolution to the cam-shaft 724. This second half-revolution pulls the link 765 to the left (Fig. 18) into the position shown. During this movement, however, the latch 763 engages the block 5 758, swings the lever 722 into its extreme left-hand position and holds it there. The movement of the jack is thus reversed, and the reverse movement continues until the small arm 770 is swung down into the position shown to 10 disengage the latch 763 to permit the spring 723 to pull the lever back into the neutral position shown, whereupon the jack comes to rest in its initial position as has been described above.

The lever 170 (Fig. 11) which serves to pull 15 down the rod 167 at the proper times, is pivoted at 779 to the frame of the machine and carries at its inner end a roll 782 (Fig. 18) which is engaged at proper times by a cam 781 on the cam-shaft 724. This cam operates during the second 20 half-revolution of the cam-shaft 724 to swing the lever 170 clockwise (Fig. 11) into position to permit its left-hand end to be engaged and held down by the latch 173, the spring 168' being tensioned by this lever movement. The hub of this 25 latch, as has been stated, is fast to the same rock-shaft 751 to which the hub of the lever 750 is also fast.

Overlap control mechanism

30

There will now be described the mechanism for operating the small arm 770 (Fig. 18), the swinging down of which stops the reverse movement of the jack by bringing the machine to rest, and determines the amount of overlap of the 35 path of the tool on the shoe. Referring first to Fig. 11, the upright shaft 61 has formed on it a worm 791 which meshes with a worm gear 793, and it is through this worm and gear that the extent of the overlap is determined by controlling the extent of reverse movement of the jack. Referring now to Figs. 12, 13, 14 and 15, the gear 793 is the outer driving member of a Horton clutch, the inner member 794 of which has the 40 usual spring-pressed rolls 795. When the upright shaft 61 is rotating in a direction to impart forward movement to the jack, the gear 793 is rotated counterclockwise, as viewed in Fig. 13, and the inner member 794 will rotate with it because of the slight friction of the balls on the inner member 794 and because there is no load on said inner member. This inner member has attached to it a cam 797 which engages a roll 45 on the lower end of a vertical arm 799 the hub of which is fast to the same rock-shaft 771 to which are also fast the hubs of the small horizontal arms 187 and 770. The arm 770, it will be remembered, disengages the latch 763 (Fig. 18) to stop the machine, while the arm 187 pulls down the link 184 (Fig. 2) which withdraws the 50 stop block 177 from beneath the arm 155. Returning now to Fig. 13, which shows the parts in the position occupied by them just after the machine has been stopped, when the upright 55 shaft 61 rotates in the forward direction, the gear 793 rotates in a counter-clockwise direction and frictionally carries with it the inner member, thereby moving the cam 797 from engagement with the arm 799. By this time, the arm 155 (Fig. 2) has been swung up, and the spring 181 swings the block 177 beneath the arm and pulls up the rod 184 thus rocking the small shaft 771 (Fig. 13) clockwise as far as a stop-screw 184' permits. Since the arm 770 is also fast to 60

75

this same rock-shaft it is swung up to free the latch 763 (Fig. 18) which it was holding down. Returning again to Fig. 13, the cam 797 continues its clockwise movement until a pin 798 projecting forward from it encounters a stop 801 which may be adjusted into various predetermined positions. The cam and the inner member 794 are then held from movement although the gear 793 continues to rotate. The cam 797 remains stationary in the position in which it was stopped until the reverse movement of the jack begins by reason of the reversal of rotation of the shaft 61. The gear 793 then moves in a clockwise direction and positively rotates the inner member 794 until the cam 797 reaches the position shown wherein it has rocked the small shaft 771 to swing down the small arms 187 and 770. Swinging down the arm 187 pulls down the rod 184 which moves the stop block 177 (Fig. 2) from beneath the arm 155 and permits the rod 161 to pull down the arm and unlock the shoe from the jack. Swinging down the small arm 770 pushes down the latch 763 (Fig. 18) to disengage the latch and permit the shifting lever 722 to be moved into neutral position to bring the jack to rest.

Referring again to Figs. 12, 13, 14 and 15, the stop member 801 is pivoted at 803 to a head at the inner end of a shaft 805, said stop being normally held in the position shown by a small spring 807. At the outer end of the rockshaft is a toothed wheel 809 between two selected teeth of which a spring-pressed locking member 811 extends. By pulling up this spring-pressed locking member 811 and grasping a hand-wheel 813, the shaft 805 may be rotated into various angular positions and may be locked in those positions by releasing the locking member 811. The wheel 809 carries two stop-pins 815 which limit its extent of rotation in both directions and thus limit the extent of the overlap which can be produced. The stop 801 (Fig. 14) is provided at its lower end with an inclined face 803' so that, if for any reason, the driving shaft of the machine is rotated backwards by hand, the stop 801 will swing in against the force of the spring 807, when the pin 798 on the cam 797 strikes it and prevents breakage of parts.

Referring to Fig. 13, a leaf-spring 817 fastened at one end to the depending arm 799 by a clamp 819 has a lower curved end extending over a small pin 821 on the cam 797. This spring, in the position of parts shown, is under some tension. Its purpose is to insure that, when the gear 793 is rotated in a counterclockwise direction the cam 797 shall always be carried with it. If this kick-back spring 817 were not provided, it might happen that the friction between the cam 797 and the roll at the lower end of the arm 799 would be sufficient to hold the cam 797 stationary when the gear 793 is rotated in the counterclockwise direction.

Referring again to Fig. 11, it has been explained that when the treadle 137 is pushed down part way the latch 173 is swung to the left to release the outer end of the lever 170 which is then pulled up to permit the shoe to be locked to the jack. It is sometimes desired to remove at once from the jack a shoe which has not been positioned properly, and to this end treadle-operated means are provided for rocking the lever 170 counterclockwise so as to swing down its outer left-hand end. This mechanism comprises a treadle 850 fast to a short rock-shaft 852 to which

is fast the hub of an arm 854 connected by a link 856 to an arm 858 pivoted on the shaft 179 and having a portion adapted, when the arm is rocked, to engage an abutment screw 860 carried by the lever 170. Thus, if the shoe is not locked in proper position in the jack, the operator may release it by depressing the treadle 850.

Operation of machine

A detailed description of the operations of the various mechanisms of the machine have been given above. There will now be given a brief description of the complete operation of the machine, exclusive of the toe cap cementing mechanism and the bottom cementing mechanism, by reference principally to Figs. 1, 2 and 3. The operator holds the shoe as shown in Fig. 1 and depresses the treadle 137 (Fig. 3). The first part of this depression swings the latch 173, frees the outer end of the lever 170 and thereby releases for upward movement the lower end of the multipart telescoping rod, the upper member 161 (Fig. 2) of which was holding down the lever 155. The spring 174 swings the lever 155 up, thereby pulling up the push-rod or release pin 149 which was preventing the shoe from being locked to the jack. The shoe is now locked to the jack as movement of the clamp 124 of the jack becomes effective to cramp the last-pin 103 in the last-pin hole of the jack. Further depression of the treadle 137 imparts a half-revolution to the cam-shaft 724 (Fig. 11). This half-revolution swings the foxing cementing tool into contact with the toe portion of the shoe through the mechanism shown in Fig. 25 and starts rotation of the shaft 61 (Figs. 1, 2) in a direction to cause forward movement of the jack by swinging the shifting lever 722 (Fig. 3) to the right. As soon as rotation of the shaft 61 starts, the mechanism shown in Fig. 13 releases the two small arms 770 and 187 (Fig. 3) and allows them to swing up. Swinging up the arm 770 releases the latch 763 so that upon the second half-revolution of the cam-shaft 724, this latch will pull the shifting lever 722 to the left to reverse the direction of rotation of the shaft 61. Swinging up the small arm 187, which is holding the stop-block 177 (Fig. 2) in the position shown, through link 184, permits the spring 181 to swing the stop block beneath the lever 155 which is then in raised position. The jack continues its forward movement with the cementing tool applying cement to the foxing area until the cam 81 (Fig. 7) on the moving jack pushes down the small slide block 77 (Fig. 3) and pulls up the link 69. This causes another half-revolution to be imparted to the cam-shaft 724 (Fig. 11). This second half-revolution withdraws the foxing cementing tool from the shoe through the mechanism shown in Fig. 25 and causes the shifting lever 722 (Fig. 3) to be swung to the left by the latch 763 whereupon reverse movement of the jack starts. This reverse movement continues until the mechanism shown in Fig. 13 swings down once more the two small arms 770, 187 (Fig. 3). Swinging down the arm 770 disengages the latch 763 from the shifting lever 722 whereupon the spring 723 pulls the shifting lever to the right until it is stopped in the neutral position shown by the latch 759. This causes the jack to come to rest in its initial position. Swinging down the small arm 187 pulls down the link 184 to withdraw the stop block 177 (Fig. 2) from beneath the lever 155. By this time the lever 170 (Fig. 3) has been swung down to the position shown in that figure and caught by the latch 173.

so that the spring in the telescoping rod, the lower end of which is shown at 167, and the upper end at 161 (Fig. 2), has been put under considerable tension. As soon therefore as the stop block 5 177 has been pulled over beneath the lever 155, the rod 161 pulls down this lever thereby pushing down the push-rod 149 to unlock the shoe from the jack.

Although the invention has been set forth as 10 embodied in a particular machine for applying cement to a shoe, it should be understood that the invention is not limited in the scope of its application to the particular machine nor to the particular operation which has been shown and de- 15 scribed.

Having thus described my invention, what I claim as new and desire to secure by Letters Patent of the United States is:

1. In a machine for operating upon a shoe 20 unit which comprises a shoe on a last around the periphery of the shoe adjacent to the bottom thereof, a jack for supporting a shoe unit, in approximately right-side-up position, said jack including relatively movable clamping members 25 for holding the unit on the jack by engagement with the top of the unit leaving the bottom of the shoe unobstructed, an operating tool, and means to produce a continuous progressive relative movement of said jack and said tool to bring 30 the tool progressively into operative relation with the whole of the peripheral bottom portion of the shoe.

2. In a machine for operating upon a shoe 35 around the periphery of the shoe adjacent to the bottom thereof, a jack for supporting a shoe on a last depending from the jack in substantially right-side-up position so as to leave the bottom of the shoe unobstructed, said jack comprising relatively movable clamping members one of 40 which engages the last in the shoe, a shoe-upper engaging member adjustable lengthwise of the shoe thereby to accommodate various sizes, and means for holding said clamping members in gripping engagement with the shoe and last, a 45 tool occupying a relatively fixed position on the machine, and means for moving said jack to carry the periphery of the shoe past the tool.

3. In a machine for operating upon a shoe 50 around the periphery of the shoe adjacent to the bottom thereof, a jack for supporting a shoe on a last depending therefrom in substantially upright position so as to leave the bottom of the shoe facing down and unobstructed, said jack comprising relatively movable clamping members one of 55 which engages the last in the shoe, a shoe-upper engaging member adjustable lengthwise of the shoe thereby to accommodate various sizes, and means for holding said clamping members in gripping engagement with the shoe and last, a 60 tool occupying a relatively fixed position on the machine, operator-controlled means for releasing said clamping means, and means for moving said jack to carry the periphery of the shoe past the tool.

65 4. In a machine for operating upon a shoe around the periphery of the shoe adjacent to the bottom thereof, a jack for supporting a shoe in substantially upright position and projecting downwardly from the jack with the lower portion 70 of the shoe left unobstructed, said jack comprising depending relatively movable clamping members constructed and arranged to permit the shoe to be raised into engagement with the jack by a simple upward movement, one of said clamping 75 members being arranged for engagement with the

end portion of the shoe, operator-controlled means for causing said clamping members to hold the shoe against the action of gravity, a tool for operating upon the lower portion of the shoe, and means for effecting relative movement between the tool and the shoe to cause the tool to act progressively upon the periphery of the shoe. 5

5. In a machine for operating upon the peripheral lower portion of a shoe, a depending post, a jack for supporting a shoe by engagement with the upper portion thereof, leaving the lower portion unobstructed and comprising clamping members movable toward one another to clamp a shoe, said jack being supported upon said post for movement to carry the periphery 15 of the shoe past an operating point, a rod extending through said post, and operator-controlled means associated with said rod above the post to effect relative movement of said shoe clamping members. 20

6. In a machine for operating upon a lasted shoe around the periphery of the shoe adjacent to the bottom thereof, a jack for supporting a shoe in right-side-up position and including a device for engagement with the top of the last 25 leaving the bottom of the shoe unobstructed, a tool for operating upon the bottom portion of the shoe, and means for turning said shoe constructed and arranged to carry successive portions of the peripheral bottom portion thereof 30 past said tool at a substantially constant linear velocity.

7. In a machine for operating upon the peripheral lower portion of a shoe, a jack for supporting a shoe by engagement with the upper 35 portion thereof leaving the lower portion unobstructed, depending means for supporting said jack for movement about a downwardly and forwardly inclined axis, a tool mounted for movement toward and away from the shoe, 40 means for moving said jack to carry successive portions of the periphery of the shoe past the tool, and means for holding said tool in operative relation to the shoe.

8. In a machine for operating upon the peripheral lower portion of a shoe, a jack for supporting a shoe in right-side-up position by engagement with the upper portion thereof leaving the lower portion unobstructed, a tool mounted for movement toward and away from the shoe 50 and arranged to occupy substantially a fixed position with respect to the machine, and means for moving said shoe constructed and arranged to carry the peripheral lower portion of the shoe past the operating tool with both turning 55 and straight-line movements thereby imparting to the shoe substantially a constant linear velocity.

9. In a machine for operating upon the peripheral lower portion of a shoe, a frame, a post 60 extending downwardly from said frame at an inclination to the vertical with its lower end unobstructed, a jack mounted for turning movement upon the lower end of said post and constructed and arranged to support a shoe in a 65 depending position by engagement with the upper portion thereof leaving the bottom peripheral portion unobstructed, a tool, and means for turning said jack to carry the periphery of the shoe past the tool. 70

10. In a machine for operating upon the peripheral lower portion of a shoe, a depending post, a sleeve mounted for rotation upon the lower end of said post, a jack slidably mounted on said sleeve for movement in a plane sub- 75

stantially normal to the axis of the sleeve, said jack having means for gripping the upper portion of a shoe depending therefrom, leaving the bottom portion thereof unobstructed, a tool, and means for causing a combined sliding and turning movement of said jack to carry the peripheral lower portion of the shoe past the tool at a substantially uniform velocity. 5

11. In a machine for operating upon the peripheral lower portion of a shoe, a depending hollow post, a sleeve mounted for rotation upon the lower end of said post, a jack slidably mounted on said sleeve for movement in a plane substantially normal to the axis of the sleeve, said jack having means for engaging the upper portion of a shoe leaving the bottom thereof unobstructed, a tool, a guide rail for said jack, and driving means extending through said post and cooperating with said rail in turning and sliding said jack to carry successive portions of the periphery of the shoe past the tool. 10

12. In a machine for operating upon the peripheral lower portion of a shoe, a depending post, a tool, a jack engaging the upper portion of a depending shoe, leaving the lower portion thereof unobstructed, and mounted for turning and sliding movements with respect to said post, said jack including a hollow frame, and means for engaging the inner and outer peripheries of said frame to cause movement of the jack to carry successive portions of the periphery of the shoe past the tool. 20

13. In a machine for operating upon the peripheral lower portion of a shoe, a depending post, a sleeve rotatably mounted upon the lower end of said post, said sleeve having a laterally projecting flange with parallel sides, a jack, for supporting the shoe by engagement with the upper portion thereof leaving the bottom unobstructed, slidably mounted upon said flange, a tool, and means for turning the jack and sliding the jack upon the flange to carry successive areas of the peripheral portion of the shoe past the tool. 30

14. In a machine for operating upon the peripheral lower portion of a shoe, a jack for supporting a shoe by engagement with the upper portion thereof, leaving the lower portion unobstructed, said jack comprising a last pin, means for cramping a last upon said pin comprising an end clamp, a bar pivoted upon parallel links for supporting said clamp for movement toward and away from the shoe, resilient means for urging said bar substantially endwise to cause the clamp to cramp the last upon the pin, and a tool for operating upon the bottom portion of the shoe. 40

15. In a machine for operating upon the peripheral lower portion of a shoe, a jack for supporting a shoe by engagement with the upper portion thereof, leaving the lower portion unobstructed, said jack comprising a frame, a last pin on said frame, a clamp for cramping a last on said pin, a pair of bell cranks on said frame, parallel bars pivoted on opposite arms of said bell cranks, said clamp being secured to one of said bars, means for operating said clamp to hold the last constructed and arranged to effect endwise movement of one of said bars, and a tool for operating upon the bottom portion of the shoe. 50

16. In a machine for operating upon the peripheral lower portion of a shoe, a jack for supporting a shoe by engagement with the upper portion thereof, leaving the lower portion unobstructed, said jack comprising a frame, a last pin on said frame, a clamp for cramping a last on said pin, 60

a pair of bell cranks on said frame, parallel bars pivoted on opposite arms of said bell cranks, said clamp being secured to one of said bars, means for effecting sidewise movement of one of said bars to release said clamp, and a tool for operating upon the bottom portion of the shoe. 65

17. In a machine for operating upon the peripheral lower portion of a shoe, a jack for supporting a shoe by engagement with the upper portion thereof, leaving the lower portion unobstructed, said jack comprising a frame, a last pin on said frame, bell cranks at opposite ends of said frame, substantially parallel bars pivoted to the respective arms of the bell cranks, one of said bars carrying a clamp member for cramping a last on said pin, said bars comprising telescoping channels, a spring for causing a clamping action substantially enclosed within said telescoping bars, and a tool for operating upon the bottom portion of the shoe. 70

18. In a machine for operating upon shoes, a release pin, a jack mounted for movement with respect to said pin, said jack including a movably mounted clamping member, a spring pulling said clamping member in one direction, and means for operating said clamping member against said spring constructed and arranged to be in operative relation with said pin in all positions of said jack. 25

19. In a machine for operating upon shoes, a release pin, a jack frame slidably mounted with respect to said pin, a movable clamping member movably supported upon said frame, a spring to urge said clamping member to operative position, and means for releasing said clamping member in opposition to said spring constructed and arranged to be in operative relation with said pin in all positions of the jack. 30

20. In a machine for operating upon shoes, a jack frame mounted for sliding and turning movement, shoe jacking means upon said frame including a member movably mounted on the frame, a jack releasing bar extending along the center line of the frame, and a release pin positioned for engagement with said bar in all positions of the frame. 40

21. In a machine for operating upon shoes, a jack mounted for movement in a plane inclined to the horizontal to carry the periphery of a shoe on the jack past an operating point, shoe clamping means on the jack, and means for releasing said clamping means and holding said jack against movement by gravity. 50

22. In a machine for operating upon shoes, a jack including releasable shoe clamping means and mounted for movement in a plane inclined to the horizontal, driving means for moving said jack to carry the periphery of a shoe on the jack past an operating point, a brake constructed and arranged to hold said jack against movement by gravity and means for releasing said shoe clamping means and applying said brake. 55

23. In a machine for operating upon shoes, a jack mounted for movement in a plane inclined to the horizontal to carry the periphery of a shoe on the jack past an operating point, separable means for driving said jack, a brake to hold said jack against movement by gravity, and means for disconnecting said separable means and applying the brake to hold the jack. 65

24. In a machine for operating upon shoes, a jack including releasable shoe clamping means and mounted for movement in a plane inclined to the horizontal, separable driving means for moving said jack to carry the periphery of a shoe on 70

75

- the jack past an operating point, a brake for holding said jack against movement by gravity, and means for disconnecting said separable driving means, releasing said shoe clamping means and applying said brake.
25. In a machine for operating upon shoes, a post, a jack mounted for sliding and rotative movement with respect to said post, shoe supporting means comprising a clamping member movably mounted upon the jack, and means extending through said post for operating said movable clamping member.
- 10 26. In a shoe machine, a jack mounted for sliding and rotative movements, a pinion for driving said jack, shoe supporting means upon the jack comprising a member movably mounted thereon, and means coaxial with said pinion for operating said movably mounted member in all positions of the frame to release the shoe.
- 15 27. In a machine for operating upon the peripheral lower portions of shoes, a jack supporting a shoe by engagement with the upper portion thereof leaving the lower portion unobstructed and having a movable clamp, a frame for said jack supported from above for sliding and rotative movements, means for moving said frame comprising a driven pinion mounted on a hollow shaft, and means for operating said jack clamp extending downwardly through the hollow shaft
- 20 25 30
- 35 28. In a machine for operating upon the peripheral portions of shoes, a tool, a jack movably mounted to carry the periphery of a shoe past the tool and including a clamping mechanism, release mechanism for said jack clamping mechanism including a spring, means operating during movement of the shoe to tension said spring, and means operative at the end of a predetermined movement of the shoe to permit the 40 spring to become effective to operate said release mechanism.
29. In a machine for operating upon the peripheral portions of shoes, a tool, a jack movably mounted to carry the periphery of a shoe past the tool and including a clamping mechanism, release mechanism for said jack clamping mechanism including a spring, means operating during movement of the shoe to tension said spring, a latch for rendering said spring ineffective, and automatic means 45 responsive to movement of the shoe for releasing said latch to permit release of the shoe.
30. In a machine for operating upon the peripheral portion of a shoe, a shoe support, means for effecting a forward and then a reverse movement of the shoe support, clamping means on said shoe support, and means responsive to movement of the support for releasing said clamping means at the end of its reverse movement.
31. In a shoe treating machine, a tool, a jack 60 mounted for movement to carry successive portions of the periphery of a shoe on the jack past the tool, said jack having a shoe-engaging member adjustable lengthwise of the shoe, driving mechanism for the jack including a continuous rack 65 movable with the jack, said rack comprising side portions and curved end portions connecting said side portions, one of said end portions being movable with respect to the side portions in accordance with the length of the shoe, said movable end portion overlapping said side portions to provide a continuous rack, and a connection between said adjustable shoe-engaging member and said movable end portion.
- 70 32. In a shoe treating machine, a tool, a jack
- mounted for movement to carry successive portions of the periphery of a shoe on the jack past the tool, driving mechanism for the jack including a continuous rack movable with the jack, said rack comprising side portions and curved end portions connecting said side portions, one of said end portions being movable with respect to the side portions in accordance with the length of the shoe, said movable end portion overlapping said side portions to provide a continuous rack, and means for holding said end portion in registering relation to the side portions comprising a key engaging the teeth of a side portion.
33. In a machine for operating upon the peripheral portion of a shoe, a tool, a jack including a frame mounted for movement to carry successive portions of the periphery of a shoe on the jack past the tool, and driving mechanism for the jack including a continuous rack mounted for movement with the jack, said rack comprising side portions having grooves intersecting the teeth thereof, and curved end portions connecting said side portions and provided with toothed projections entering said grooves and arranged to register with the teeth of the side portions thereby to provide a continuous rack.
34. In a machine for operating upon the peripheries of shoes, a tool, a jack mounted for movement to carry successive portions of the periphery of the shoe past the tool, and driving mechanism for the jack including a continuous internal rack movable with the jack, said continuous rack comprising grooved substantially parallel side portions and curved end portions, a pinion meshing with said rack rotatable about an axis eccentric to the center of curvature of an end portion, and means for supporting said jack comprising a pivoted member slidable in said grooved portions.
35. In a machine for operating upon the peripheries of shoes, a tool, a jack mounted for movement to carry successive portions of the periphery of the shoe past the tool, a sleeve constructed and arranged to support said jack for sliding and rotative movements in a single plane, and driving mechanism for said jack comprising a continuous internal rack and a pinion for driving said rack rotatable about an axis eccentric to the axis of said sleeve.
36. In a machine for operating upon the peripheries of shoes, a tool, a jack mounted for movement to carry successive portions of the periphery of the shoe past the tool, a member pivoted on the machine extending heightwise of the shoe away from the bottom thereof, said jack being provided with a groove extending substantially parallel to the bottom of the shoe and adapted slidably to receive a portion of said pivoted member to support the jack, and means for moving the jack to carry the shoe past the tool constructed and arranged to slide the jack on the pivoted member and to turn the jack with the pivoted member about the axis thereof.
37. In a machine for operating upon the peripheral portions of shoes, a tool, a jack mounted for swinging and sliding movements to carry the periphery of a shoe on the jack past the tool, reversible driving mechanism for said jack, and means including a cam carried by the jack for controlling said driving mechanism.
38. In a machine for operating upon the peripheral portions of shoes, a tool, a jack mounted for swinging and sliding movements to carry the periphery of a shoe on the jack past the tool, re-

versible driving mechanism for said jack, and means including a cam adjustably secured to said jack for controlling said driving mechanism.

39. In a machine for operating upon the peripheral portions of shoes, a tool, a jack mounted for swinging and sliding movements to carry the periphery of a shoe on the jack past the tool, automatic mechanism for driving said jack in repeated cycles, and means including a cam secured to the jack for determining the stopping position, which is the same as the starting position, of the jack.

40. In a machine for operating upon the peripheral portions of shoes, a tool, a jack mounted for swinging and sliding movements to carry the periphery of a shoe on the jack past the tool, said jack including an adjustable member the position of which is determined by the length of the shoe, reversible driving mechanism for said jack, and means including a cam carried upon said adjustable member for controlling said reversible driving mechanism to change the effect thereof.

41. In a machine for operating upon the peripheral portions of shoes, a tool, a jack mounted for swinging and sliding movements to carry the periphery of a shoe on the jack past the tool, reversible driving mechanism for said jack, and means including a member movable in response to movement of the jack for controlling said driving mechanism, said controlling means also comprising a broken connector, and means responsive to movement of the driving mechanism for conditioning said connector.

42. In a machine for treating the peripheral portion of a shoe, a tool, a jack mounted for sliding and rotating movement to carry the periphery of a shoe on the jack past the tool, and means for controlling the movement of the jack comprising a guide rail and a driven rotating member, said guide rail comprising yieldingly supported members for absorbing the shock when the jack is rotated into contact with the guide rail.

43. A machine of the class described having, in combination, a liquid-applying member occupying a substantially fixed position in the machine, means for supplying liquid thereto, a carrier including a member for gripping a shoe part, a shoe-part-engaging portion of said carrier being adjustable with respect to said carrier to provide for shoe parts of different lengths, and means for imparting movements of translation and rotation to the carrier to cause the shoe part to move past the liquid-applying member to be coated thereby.

44. A machine of the class described having, in combination, a liquid-applying member occupying a substantially fixed position in the machine, means for supplying liquid thereto, a carrier including a member for gripping a shoe part, a shoe-part-engaging portion of said carrier being adjustable with respect to said carrier to provide for shoe parts of different lengths, and means for imparting bodily and angular movements to the carrier to cause the shoe part to move past the liquid-applying member to be coated thereby.

45. A machine of the class described having, in combination, a receptacle containing a supply of liquid, a liquid-applying member supplied therefrom, a movable carrier including means for gripping a shoe part and maintaining the surface thereof to be coated inclined to the horizontal, a shoe-part-engaging portion of said carrier being adjustable with respect to said gripping means to provide for shoe parts of different

lengths, and means for imparting movement to the carrier and gripping means to cause successive peripheral portions of the shoe part to traverse the liquid-applying means.

46. A machine of the class described having, in combination, a receptacle containing a supply of liquid, a liquid-applying member supplied therefrom, a movable carrier including means for gripping a shoe part and maintaining the surface thereof to be coated inclined to the horizontal, a shoe-part-engaging portion of said carrier being adjustable with respect to said gripping means to provide for shoe parts of different lengths, and means for imparting bodily and angular movements to the carrier and gripping means to carry the peripheral portion of the shoe part past the liquid-applying means.

47. A machine of the class described having, in combination, a receptacle containing a supply of liquid, a liquid-applying member supplied therefrom, means for holding a shoe part so that its face adjacent to the liquid-applying member is angularly related to the horizontal and liquid is applied to the shoe part at a level above a corner thereof, and means for moving the holding means first in a substantially straight path and then in a curved path to cause the shoe part to move past the liquid-applying means.

48. A machine of the class described having, in combination, a receptacle containing a supply of liquid, a liquid-applying member supplied therefrom, means for holding a shoe part so that its face adjacent to the liquid-applying member is angularly related to the horizontal and liquid is applied to the shoe part at a level above a corner thereof, and means for moving the holding means first in a substantially straight path, then in a curved path, and then again in a substantially straight path to cause the shoe part to move past the liquid-applying means.

49. A machine of the class described having, in combination, a receptacle containing a supply of liquid, a liquid-applying member supplied therefrom, means for holding a shoe part having a rounded end with a locality on the margin exposed to the action of the liquid-applying member, and means for moving the shoe part in approximately a straight line past the applying member to coat the margin along one edge thereof, for swinging the shoe part angularly to coat the margin around the rounded end, and for thereafter moving the shoe part in approximately a straight line past the applying member to coat the margin along another edge, the holding means being constructed and arranged to maintain the surface to be coated in a position angularly related to the horizontal such that the liquid applied tends to run down toward a corner thereof.

50. In a machine for operating upon the peripheral lower portion of a shoe, means for supporting a shoe for turning movement to carry successive portions of the periphery past an operating point, means for driving said turnable supporting means in forward and reverse directions, and control mechanism including means moving with the shoe for changing the direction of movement of the shoe.

51. In a machine for operating upon the peripheral lower portion of a shoe, means for supporting a shoe for turning movement to carry successive portions of the periphery past an operating point, means for driving said turnable supporting means in forward and reverse directions, control mechanism including means mov-

- ing with the shoe for changing the direction of rotation of the shoe, and adjustable means for controlling the extent of turning movement of the shoe in one direction.
52. In a machine for operating upon the peripheral lower portion of a shoe, means for supporting a shoe for turning movement to carry successive portions of the periphery past an operating point, means for driving said turnable supporting means in forward and reverse directions, control mechanism including means moving with the shoe for changing the direction of rotation of the shoe, and adjustable means for controlling the extent of movement of the shoe in 15 the reverse direction.
53. In a machine for operating upon the peripheral lower portion of a shoe, means for supporting a shoe for turning movement to carry successive portions of the periphery past an operating point, means for driving said turnable supporting means in forward and reverse directions, means for reversing the direction of rotation of the shoe, and adjustable means including a cam driven by a one-way clutch for controlling the extent of movement of the shoe in one direction thereby to control the overlap.
54. In a machine for operating upon the peripheral lower portion of a shoe, means for supporting a shoe for turning movement to carry successive portions of the periphery past an operating point, means for driving said supporting means in forward and reverse directions, means for reversing the direction of rotation of the shoe, adjustable means for controlling the extent of movement of the shoe in one direction thereby to control the overlap including a cam driven by a one-way clutch, and an adjustable stop cooperating with said cam to determine the extent of movement thereof in one direction.
55. In a machine for operating upon the periphery of the lower portion of a shoe, means for supporting a shoe constructed and arranged to present successive portions of the periphery to an operating position, power means for moving said shoe supporting means in opposite directions in one of which the extent of movement includes more than the whole periphery of the shoe, and an overlap mechanism for determining the extent of the overlap comprising a cam, im- 45 positive means driving said cam away from its operating point to an adjustable starting position, and positive means for returning said cam from the starting position to an operating position.
56. In a machine for operating upon the periphery of the lower portion of a shoe, means for supporting a shoe constructed and arranged to present successive portions of the periphery to an operating position, power means for moving said shoe support in opposite directions in one of which the extent of movement includes more than the whole periphery of the shoe, and an overlap mechanism for determining the extent of the overlap comprising a cam, a kick-off spring for 60 moving said cam away from the operating point, and positive driving means for returning said cam to the operating point.
57. In a machine for operating upon the periphery of the lower portion of a shoe, means for supporting a shoe constructed and arranged to present successive portions of the periphery to an operating position, power means for moving said shoe support in opposite directions in one of which the extent of movement includes more 70 than the whole periphery of the shoe, and an overlap mechanism for determining the extent of the overlap comprising a cam, means for driving said cam including a one-way clutch, and operator-controlled means for determining the starting position of said cam as the cam is carried frictionally away from the starting point.
58. In a machine for operating upon the peripheral lower portion of a shoe, a jack for supporting a shoe constructed and arranged to carry successive portions of the periphery of the shoe past an operating point, an operating tool, means for supporting said tool for movement toward and away from the shoe, driving mechanism for moving said jack in reverse directions, and control mechanism to move said tool into 15 contact with the shoe, to cause the driving mechanism to drive said jack to carry more than the whole periphery of the shoe past the tool, to withdraw the tool, to cause the driving mechanism to move the shoe in the reverse direction, 20 and to interrupt the reverse movement at a predetermined time thereby to control the overlap by controlling the starting position of the shoe.
59. In a machine for operating upon the peripheral lower portion of a shoe, a jack for supporting a shoe constructed and arranged to carry successive portions of the periphery of the shoe past an operating point through a full periphery plus an overlap, an operating tool, means for supporting said tool for movement toward 25 and away from the shoe, driving mechanism for moving said jack in reverse directions, cam-operated means for moving the tool into contact with the shoe and away from the shoe at the end of a period of treatment, means movable 30 with the shoe for controlling the direction of movement of the shoe, and operator-controlled means for determining the amount of the overlap comprising means for determining the extent of movement of the shoe in one direction.
60. In a foxing cementing machine, means for supporting a shoe in substantially upright position by engagement with the top of the shoe leaving the bottom unobstructed, an applying tool adapted to flow cement in a stream upon 45 the unobstructed peripheral lower portion of the shoe, an underlying receptacle, and means for circulating cement from said receptacle through said applying tool, said tool and said shoe being mounted for relative traversing movement to 50 enable the periphery of the shoe to be coated with cement.
61. In a foxing cementing machine, an elongated nozzle having a curved profile whereby curved cross-sections of various portions of the 55 foxing area of the shoe may be brought into close relation to the profile of said nozzle, and means for forcing a sheet of cement from said elongated nozzle across a short gap to the shoe.
62. In a foxing cementing machine, an elongated applying nozzle having a curved profile, means for supporting said nozzle, and means for supporting a shoe, said supporting means being relatively movable to permit the curved nozzle to be brought into close relation with the vertical extent of the foxing area at all portions of the shoe.
63. In a foxing cementing machine, an elongated nozzle adapted to deliver a sheet-like stream of cement against the foxing area of a 70 shoe, said nozzle having a ridged portion adapted to be dragged over the surface of a shoe and an opening through which the cement flows located at one side of said ridge.
64. In a foxing cementing machine, an apply- 75

ing nozzle and a shoe support mounted for relative movement to carry successive portions of the foxing area of the shoe past the nozzle, said nozzle having a ridged portion adapted to be 5 dragged along the foxing area and an opening at the leaving side of said ridge, and means for forcing cement through said opening directly upon the foxing area of the shoe.

65. In a foxing cementing machine, a vertically elongated nozzle adapted to deliver a sheet-like stream of cement upon a shoe, and a guard plate at that end of said nozzle which corresponds to the top edge of the foxing area thereby to prevent upward spread of the cement.

15 66. In a foxing cementing machine, an elongated nozzle adapted to deliver a sheet-like stream of cement upon a shoe, a guard plate at that end of said nozzle which corresponds to the top edge of the foxing area thereby to prevent 20 upward spread of the cement, and an anti-friction roll overlying said guard plate and extending slightly beyond the edge of the guard plate for contact with the shoe.

67. In a foxing cementing machine, an elongated nozzle comprising a recessed body portion, means for supplying cement under pressure to said body portion, and a plurality of outlet openings spaced along the length of the nozzle 25 through which cement is forced in intermingling streams against a shoe.

68. In a foxing cementing machine, a cement-applying nozzle and a shoe support mounted for relative movement to cause the nozzle to traverse the foxing area of a shoe on the support, said nozzle extending transversely of the foxing area and mounted for swinging movement about an axis substantially coincident with the upper edge of the foxing area, and means for supplying cement to said nozzle.

40 69. In a foxing cementing machine, means for supporting a shoe in substantially upright position, a nozzle extending substantially vertically transversely of the foxing area, means for causing relative movement between a shoe on said support and said nozzle to cause the nozzle to traverse the foxing area, and means for supporting said nozzle for swinging movement about an axis substantially coincident with the upper edge of the foxing area whereby the nozzle will 45 lie close to the shoe both in the projecting toe and heel portions thereof and in the undercut shank portions.

70. In a foxing cementing machine, an elongated nozzle adapted to deliver a stream of cement extending substantially across the foxing area, a guideway for supporting said nozzle for swinging movement about an axis approximately at the upper edge of the foxing area to bring the nozzle into positions closely adjacent to the 50 foxing area at all parts of the shoe, and means for supplying cement to said nozzle in all positions of swinging movement of the same.

71. In a foxing cementing machine, a nozzle guided for swinging movements about an axis substantially coincident with the upper edge of the foxing area, and a pipe for supplying cement to said nozzle also pivoted about the same axis.

72. In a foxing cementing machine, a nozzle arranged to deliver cement in a stream, and a curved guideway supporting said nozzle for swinging movement, said guideways comprising a channeled member opening away from the stream of cement.

73. In a foxing cementing machine, a nozzle 75 adapted to deliver a stream of cement, a curved

guideway supporting said nozzle for swinging movement and comprising a channeled member opening away from said stream of cement, and hooked arms upon the nozzle extending around one side of the channel and entering the groove 5

74. In a foxing cementing machine, a nozzle adapted to deliver a stream of cement, a channeled guideway, and spaced guide rolls attached to said nozzle and mounted for movement in said 10 guideway, whereby the nozzle may move to coact closely with the varying shapes of different parts of a shoe.

75. In a foxing cementing machine, a nozzle for delivering a stream of cement, a curved, channeled guideway opening away from the stream of cement, hooked arms on the nozzle bearing rolls in the guideway, and means for delivering cement to said nozzle in all positions of the same.

76. In a foxing cementing machine, means for supporting a shoe in substantially upright position, a cement-applying tool in cooperative relation with the foxing area of the shoe, the tool and said support being relatively movable to cause the tool to traverse the foxing area of the 20 shoe, said tool comprising a pivoted portion, means for forcing cement through said pivoted portion, and means for tilting said pivoted portion to cause it to cooperate with the varied inclinations of successive portions of the foxing 30 area.

77. In a foxing cementing machine, a support for a shoe, a cement-applying tool, said tool and said shoe support being relatively movable to cause the tool to traverse the foxing area of a 35 shoe on the support, said tool being mounted for movement toward and away from the shoe and heightwise of the shoe, and having a nozzle mounted for rocking movement to accommodate the various curvature of the foxing area.

78. In a foxing cementing machine, a support for a shoe, a cement-applying tool, said tool and said shoe support being relatively movable to cause the tool to traverse the foxing area of a shoe on the support, and a support for said tool 45 mounted for movement to carry the tool toward and away from the shoe and for movement heightwise of the shoe, said tool comprising an applying member mounted on said tool support for swinging movement about an axis which, when 50 the tool is in contact with the shoe, will substantially coincide with the upper edge of the foxing area.

79. In a foxing cementing machine, means for supporting a shoe constructed and arranged to leave the peripheral bottom portion of the shoe unobstructed, a cement-applying tool, a support for said tool movable toward and away from a shoe on the shoe support, said tool being yieldable heightwise of the shoe, and an inclined bottom guide associated with said tool and constructed and arranged to draw the tool down to the height of the foxing area as the tool support approaches the shoe.

80. In a foxing cementing machine, a support 65 for a shoe adapted to hold it in substantially upright position, a cement-applying tool, said tool and said shoe support being relatively movable to cause the tool to traverse the foxing area of a shoe on the support, a support for the tool movable toward and away from the shoe, and a shoe bottom engaging member mounted on said tool support adapted to project under said shoe bottom, said member being inclined with respect to the shoe bottom and constructed and arranged 70 75

to guide said tool into engagement with the shoe in a predetermined relation to the bottom of the shoe.

81. In a foxing cementing machine, a support for a shoe adapted to hold it in substantially upright position, a cement-applying tool, said tool and said shoe support being relatively movable to cause the tool to traverse the foxing area of the shoe, a tool-supporting arm movable toward and away from the shoe and movable heightwise of the shoe, and a shoe bottom engaging member projecting from said arm inclined with respect to the bottom of the shoe and adapted gradually to guide the tool into engagement with the shoe in exactly a predetermined relation to the bottom of the shoe.

82. In a foxing cementing machine, a support for a shoe, a cement-applying tool, said tool and said shoe support being relatively movable to cause the tool to traverse the foxing area of the shoe, a tool-carrying arm swingable about a plurality of angularly related axes, and a nozzle guided for swinging movement upon the arm thereby to bring the nozzle into close relation to the foxing area of the shoe as the tool traverses the shoe.

83. In a foxing cementing machine, a support for a shoe, a cement-applying tool, said tool and said shoe support being relatively movable to cause the tool to traverse the foxing area of the shoe, a tool-carrying arm swingable to carry the tool toward and away from the shoe and yieldable heightwise of the shoe, said arm carrying a bottom rest inclined with respect to the bottom of the shoe, an applying nozzle, means on said arm for guiding said nozzle for swinging movement, and means for holding the outlet portion of said nozzle in close relation to the foxing area.

84. In a foxing cementing machine, a support for a shoe, a cement-applying tool, said tool and said shoe support being relatively movable to cause the tool to traverse the foxing area of the shoe, an arm supporting said tool movable to carry the tool toward and away from the shoe, a cam-operated lever having a lost motion connection with said arm, and a spring connected with the arm extending lengthwise of said lever and secured to the cam-operated end of the lever whereby the extension of the spring to accommodate variations in the contour of the shoe is minimized.

85. In a foxing cementing machine, a support for a shoe, a cement-applying tool, said tool and said shoe support being relatively movable to cause the tool to traverse the foxing area of the shoe, a tool-carrying arm swingable with a shaft, a cam-operated lever having a lost-motion connection to said shaft constructed and arranged positively to withdraw the tool from the shoe, and a spring connected to said shaft extending lengthwise of said lever and secured to the cam-operated end of the lever for holding the tool in contact with the shoe when the tool-carrying arm is free from the positive control of the lever.

86. In a foxing cementing machine, a support constructed and arranged to hold a shoe in substantially upright position, a cement-applying tool, said tool and said shoe support being relatively movable to cause the tool to traverse the foxing area of the shoe, a tool-carrying arm swingable laterally and heightwise of the shoe, means for moving said arm to carry the tool away from the shoe, and cam-operated means for depressing the tool-carrying end of the arm below

the level of the bottom of the shoe as it is withdrawn from the shoe.

87. In a foxing cementing machine, a support constructed and arranged to hold a shoe in substantially upright position, a cement-applying tool, said tool and said shoe support being relatively movable to cause the tool to traverse the foxing area of the shoe, a tool support, a shoe-bottom-engaging member rigidly mounted upon said tool support, said member being inclined outwardly from the tool support and downwardly with respect to the bottom of the shoe, and a nozzle associated with said bottom-engaging member and underlying the shoe to direct cement upon the bottom of the shoe.

88. In a foxing cementing machine, a support constructed and arranged to hold a shoe in substantially upright position, a cement-applying tool, said tool and said shoe support being relatively movable to cause the tool to traverse the foxing area of the shoe, a tool support, a shoe-bottom-engaging member on said tool support, said member being inclined outwardly from the tool support and downwardly with respect to the bottom of the shoe, and a nozzle for directing cement upon the bottom of the shoe associated with said bottom-engaging member, the outlet opening of said nozzle being arranged upon the leaving side of said bottom-engaging member.

89. In a foxing cementing machine, a support for a shoe to hold the shoe in substantially upright position, a cement-applying tool, said tool and said shoe support being relatively movable to cause the tool to traverse the foxing area of the shoe, an outwardly-projecting bottom-engaging member associated with said tool, said member being inclined outwardly and downwardly with respect to the bottom of the shoe, a nozzle for directing cement upon the bottom of the shoe associated with said bottom-engaging member, the outlet opening of said nozzle being arranged upon the leaving side of said bottom-engaging member, and a spreader upon the leaving side of said nozzle.

90. In a machine of the class described, a shoe support for holding a shoe in substantially upright position, a tool for treating the peripheral lower portion of the shoe on the support, said tool and said support being relatively movable to carry the tool around the periphery of the shoe, a tool-carrying member yieldable heightwise of the shoe, and a bottom-engaging member movable with the tool and pivoted about an axis extending substantially radially of the shoe, said bottom-engaging member having sufficient length to engage the shoe in front of and to the rear of the shank portion thereby to guide the tool along the shank portion in a straight line.

91. In a machine of the class described, a shoe support for holding a shoe in substantially upright position, a tool for treating the peripheral lower portion of the shoe on the support, said tool and said support being relatively movable to carry the tool around the periphery of the shoe, a tool-carrying member yieldable heightwise of the shoe, said tool-carrying member having a pivot substantially normal to the periphery of the shoe, and a bottom-engaging plate mounted on said pivot, said plate being longer than the shank portion of the shoe.

92. In a machine of the class described, a shoe support for holding a shoe in substantially upright position, a tool for treating the peripheral lower portion of the shoe on the support, said

tool and said support being relatively movable to carry the tool around the periphery of the shoe, a tool-carrying member yieldable heightwise of the shoe, said tool-carrying member having a 5 pivot substantially normal to the periphery of the shoe, a bottom-engaging plate mounted on said pivot, said plate being longer than the shank portion of the shoe, and yieldable means tending to hold said plate in a predetermined relation to 10 said tool-carrying member.

93. In a machine of the class described, a shoe support for holding a shoe in substantially upright position, a tool for treating the peripheral lower portion of the shoe on the support, said 15 tool and said support being relatively movable to carry the tool around the periphery of the shoe, a tool-carrying member yieldable heightwise of the shoe, said tool-carrying member having a pivot substantially normal to the periphery 20 of the shoe, and a shoe-bottom-engaging plate mounted on said pivot, said plate being longer than the shank portion of the shoe and inclined with respect to its pivot and with the edge thereof away from the tool support lower with respect 25 to the shoe bottom than the other edge.

94. In a machine of the class described, a shoe support for holding a shoe in substantially upright position, a tool for treating the peripheral lower portion of the shoe on the support, said 30 tool and said support being relatively movable to carry the tool around the periphery of the shoe, a tool-carrying member yieldable heightwise of the shoe, and spaced shoe-bottom-engaging members constructed and arranged to coact 35 respectively with an end portion of the shoe and with an intermediate portion of the shoe.

95. In a machine of the class described, a shoe support for holding a shoe in substantially upright position, a tool for treating the peripheral lower portion of the shoe on the support, said 40 tool and said support being relatively movable to carry the tool around the periphery of the shoe, a tool-carrying member yieldable heightwise of the shoe, and three spaced shoe-bottom-engaging members one of which coacts with the 45 toe and heel portions of the shoe and the others of which coact alternately with the shoe to control the tool along the shank portion of the shoe.

96. In a machine of the class described, a shoe 50 support for holding a shoe in substantially upright position, a tool for treating the peripheral lower portion of the shoe on the support, said tool and said support being relatively movable to carry the tool around the periphery of the shoe, a tool-carrying member yieldable heightwise of the shoe, and spaced shoe-bottom-engaging members constructed and arranged to control the relation of the tool to the shoe as it passes 55 along the shank portion thereof, one of said members acting to control the relation when the tool is operating upon the left side of the shoe and the other operating to control the relation when it is operating along the right side thereof.

97. In a machine of the class described, a shoe 60 support for holding a shoe in substantially upright position, a tool for treating the peripheral lower portion of the shoe on the support, said tool and said support being relatively movable to carry the tool around the periphery of the shoe, a tool-carrying member yieldable heightwise of the shoe, adjustable spaced shoe-bottom-engaging members adapted to cooperate with 65 different portions of the shoe thereby to control the action of the tool along the sides of the shoe, 70 and readily interchangeable pairs of shoe-bot-

tom-engaging members constructed and arranged for control of the tool for a right shoe and a left shoe respectively.

98. In a cementing machine, a support for a 5 shoe, tools, said support and said tools being relatively movable to cause the tools to traverse the periphery of the shoe, the tools comprising means for directing streams of cement simultaneously upon the foxing area of the shoe and the bottom of the shoe in amounts greater than needed for 10 coating the shoe, and means for recirculating the excess cement.

99. In a cementing machine, a support for a 15 shoe, tools, and means for imparting swinging and sliding movements to said support to carry the periphery of the shoe past the tools, said tools comprising means for applying cement simultaneously to the foxing area, the bottom of the shoe and the toe cap area of the shoe.

100. In a cementing machine, a shoe support 20 for holding a shoe in substantially upright position with its bottom facing down and unobstructed, and cement-applying tools, said tools and said shoe support being relatively movable to cause the tools to traverse the periphery of 25 the shoe, the tools comprising nozzles for directing streams of cement upon the foxing area and the bottom of a shoe on the support.

101. In a cementing machine, a shoe support 30 for holding a shoe in substantially upright position with its bottom facing down and unobstructed, and cement-applying tools, said tools and said shoe support being relatively movable to cause the tools to traverse the periphery of 35 the shoe, the tools comprising nozzles for directing streams of cement upon the foxing area, the bottom of the shoe and the toe-cap area of the shoe on the support.

102. In a cementing machine, a shoe support 40 for holding a shoe in substantially upright position with its bottom facing down and unobstructed, and cement-applying tools, said tools and said shoe support being relatively movable to cause the tools to traverse the periphery of 45 the shoe, the tools comprising nozzles for directing streams of cement simultaneously upon the foxing area and the toe-cap area of the shoe on the support.

103. In a cementing machine, a shoe support 50 for holding a shoe in substantially upright position with its bottom facing down and unobstructed, and cement-applying tools, said tools and said shoe support being relatively movable to cause the tools to traverse the periphery of 55 the shoe, the tools comprising nozzles for directing streams of cement simultaneously upon the bottom of a shoe and upon the toe-cap area at the top of the toe of a shoe on the support.

104. In a cementing machine, means for supporting a shoe part in position to drain without 60 coating other than the intended area thereof, means for applying cement to a portion of said shoe part, a receptacle underlying the applying tool and the shoe part, and a drain board overlying part of said receptacle and coacting therewith to provide a narrow passage communicating with the receptacle.

105. In a cementing machine, a shoe support, 65 a tool for forming a curtain of cement, and means for effecting relative movement of the tool and the shoe support to cause the toe of the shoe to move through the curtain of cement thereby to deposit cement upon the toe cap area.

106. In a cementing machine, a shoe support 70 movable to carry successive portions of the pe- 75

periphery of a shoe past an operating point, a movably mounted cement-applying tool, and means responsive to movement of a shoe on the support for moving said tool into operative relation to the shoe during only a portion of the movement of the shoe support.

107. In a shoe cementing machine, a shoe support movable to carry successive portions of the periphery of a shoe past an operating point, a movably mounted cement-applying tool, and machine-operated means associated with said movable shoe support for moving said tool to a position overlapping the path of movement of the shoe during a portion of the movement of the 15 shoe.

108. In a shoe cementing machine, a shoe support movable to carry successive portions of the periphery of a shoe past an operating point, a movably mounted cement-applying tool, means responsive to movement of the shoe for moving the tool into operative relation to the shoe, and other means responsive to a movement of the shoe for carrying said tool out of operative relation to the shoe.

109. In a cementing machine, a shoe support mounted for successive turning and straight-line movements to carry successive portions of the periphery of a shoe on the support past an operating point, a movably mounted cement-applying tool, means responsive to turning movement of the shoe support for moving said tool into operative relation to the shoe, and means responsive to straight-line movement of the shoe for moving said tool out of operative relation to the 35 shoe.

110. In a cementing machine, an operating tool, a shoe support mounted for movement to carry the periphery of the shoe past the operating tool, a tool for applying cement to the toe-cap area 40 of the shoe positioned to coat the toe-cap area during forward movement of the shoe toward said cement-applying tool, and means responsive to movement of the shoe to carry said cement-applying tool out of relation to the shoe after 45 the desired area has been coated.

111. In a cementing machine, an operating tool and a shoe support mounted for relative movement to carry the shoe past the operating tool, the tool comprising a toe-cap cement-applying 50 device positioned to apply cement to the toe-cap area of the shoe during said relative movement, and means for causing said device to wipe over the top of the toe to even the cement during a portion of said relative movement.

112. In a cementing machine, an operating position, a shoe support mounted for alternate turning and straight-line movements to carry successive portions of the periphery of the shoe 60 past the operating position, an applying tool for delivering a stream of cement upon the toe-cap area during a portion of the straight-line movement of the shoe, said tool being mounted for retrograde movement away from the shoe, and means on the tool for spreading the coating of cement during the retrograde movement of the 65 tool.

113. In a shoe cementing machine, a tool for producing a stream of cement, said tool also 70 embodying a cement-distributing device, and means for producing relative movement between said tool and a shoe to carry the shoe through the stream of cement to coat the toe-cap area and then to cause the distributing device to even the 75 coating of cement.

114. In a toe-cap cementing machine, a cement-applying tool, means for supporting said tool for movement vertically toward the shoe and laterally toward and away from the shoe, and means responsive to movement of a shoe presented to said tool for lowering said tool into contact with the shoe and moving it laterally away from the shoe.

115. In a toe-cap cementing machine, a shoe support movable to carry a shoe in a predetermined path, a cement-applying tool comprising means for delivering a stream of cement, distributing means, means to move the shoe to carry the toe-cap area through the stream of cement, and means for then moving the tool away from the shoe to cause the distributing means to even coating of cement.

116. In a toe-cap cementing machine, an applying tool, a movably mounted shoe support, a support for said tool movable to carry it into and out of the path of movement of a shoe on the support, means for moving the shoe support to carry the toe-cap area under the tool, bringing the tool into contact with the shoe, and means for effecting retrograde movement of the 25 tool support to cause the tool to drag over the toe-cap area of the shoe.

117. In a toe-cap cementing machine, an applying tool, a movably mounted shoe support, a support for said tool movable into and out of 30 the path of movement of a shoe on the support and heightwise toward and away from the top of the toe of said shoe, means for moving the shoe support to carry the toe-cap area under the tool, means responsive to movement of the 35 shoe for causing the tool then to move heightwise into contact with the shoe, and means for effecting a retrograde movement of the tool support to cause the tool to drag over the toe-cap area.

118. In a toe-cap cementing machine, a movable shoe support, a cement-applying tool adapted to deliver cement in a stream, a movable support for said tool, means responsive to movement of said shoe support to start the flow of 45 cement, and other means responsive to movement of the shoe on the support for carrying the tool away from the shoe and interrupting the flow of cement.

119. In a toe-cap cementing machine, a cement-applying tool having a control valve, an abutment on the machine, a valve-control member adapted to be brought into contact with the abutment to open the valve, means for moving the tool to operating position thereby to bring 55 the valve member against the abutment to open the valve, and a spring for closing the valve when the tool is moved away from the abutment.

120. In a cement-applying tool, a cement-spreading device comprising a flexible wiper and 60 rigid means comprising spaced members partly surrounding the wiper to determine the spacing thereof from the shoe as the device is brought into engagement with the shoe, and resilient means assuring even contact of said device with 65 the shoe.

121. In a cement-applying tool, a flexible wiper, and a rigid member wound loosely about the wiper to provide a series of spaces between the wiper and the work.

122. In a cement-applying tool, a flexible wiper, a rigid member wound loosely about the wiper to provide a series of spaces between the wiper and the work, and resilient means for pressing the wiper toward the work.

support to carry successive portions of the work past the tool.

123. In a cement-applying tool, a flexible wiper, a loose coil of wire surrounding said wiper, a spring member for urging said wiper toward the work, and means for attaching the wire to the 5 spring member thereby to support the wiper upon the spring member.

124. In a shoe-cementing machine, a tool and a shoe support relatively movable to carry the tool over successive portions of the area to be 10 coated, said tool comprising a wiper adapted to be dragged over the surface of the work during relative movement between the tool and the shoe, separated spacers between the wiper and the work, said tool also including a nozzle curved to fit the 15 portion of a shoe to be coated and having a series of outlets for delivering streams of cement alongside the wiper upon the leading side of the tool so that the wiper will be effective during relative movement between the tool and the shoe to even 20 the coating of cement applied to the tool.

125. In a shoe-cementing machine, a cement-applying tool and a shoe support relatively movable to carry the tool over the area of a shoe on the support which is to be cemented, said tool having a groove, and a wiper located in said groove, said tool also having apertures alongside the groove to deliver a stream of cement upon the shoe to be evened by the wiper.

126. In a toe-cap cementing machine, an applying tool comprising a casing having a curved periphery, said peripheral portion having an outlet opening for cement and a groove, a wiper positioned in said groove, resilient means back of the wiper to hold it in uniform contact with the shoe, and resilient metallic members between the wiper and the shoe for determining the depth of cement as the wiper evens the applied coating.

127. In a toe-cap cementing machine, a tool mounted for movement about substantially upright and substantially horizontal axes, a spring urging the tool to move about an upright axis, a latch for holding the tool against movement by the spring, and means responsive to movement of a shoe being presented to the tool for simultaneously dropping the tool upon the shoe and releasing the latch to allow the tool to be drawn away from the shoe.

128. A machine for operating upon parts of boots and shoes having in combination a post, a sleeve mounted for rotation upon the post, a work support slidably mounted on the sleeve for movement in a plane substantially perpendicular to the axis of the sleeve, a tool, and means for causing sliding and turning movements of said work

support to carry successive portions of the work past the tool.

129. A machine for operating upon parts of boots and shoes having in combination a post, a sleeve mounted for rotation upon the post, a work support slidably mounted on the sleeve for movement in a plane substantially perpendicular to the axis of the sleeve, a tool, a guide rail for the work support and driving means extending through the post and cooperating with the rail in sliding and turning said work support to carry successive portions of the work past the tool.

130. A machine for operating upon parts of boots and shoes having in combination a post, a sleeve rotatably mounted on the post, said sleeve having a laterally projecting flange, a work support slidably mounted on the flange, a tool, and means for turning the work support and sliding it on the flange to carry successive portions of the work past the tool.

131. A machine for operating upon parts of boots and shoes having in combination a tool, a work support and means for moving said work support to carry successive portions of the work past the tool, said means comprising a rotatable sleeve upon which the work support is mounted for sliding movement, driving mechanism for said work support comprising a member provided with a continuous internal rack, a pinion rotatable about an axis eccentric to the axis of the sleeve for driving the rack, and a guide engaging the outside of the rack member.

132. A machine for operating upon parts of boots and shoes having in combination a tool, a work support, means for imparting to the work support turning movements and movements of translation to carry successive portions of the work past the tool, said work support comprising a work clamp and yielding means urging the clamp into work engaging position, and operator-controlled means constructed and arranged to be effective in all positions of the work support to move the clamp into work-releasing position.

133. A machine for operating upon parts of boots and shoes having in combination a work support, an operating tool normally held in inoperative position, means for moving the tool into operative position, means for imparting movement to the work support to carry successive portions of the work past the tool, means for withdrawing the tool from the work, and a member carried by the work support for causing actuation of said last-named means.

ERNEST W. STACEY.
